CIRCULAR MULTIFEED HOSIERY KNITTING MACHINE AND METHOD OF OPERATING SAME

John J. McDonough, Belmont, N. H., assignor to
 Scott & Williams, Incorporated, Laconia, N. H.,
 a corporation of Massachusetts

Application April 26, 1948, Serial No. 23,284

58 Claims. (Cl. 66—41)

1

This invention relates to circular multi-feed hosiery knitting machines and method of operating same, and more particularly to such machines when adapted to knit at a plurality of feeds on both rotary and reciprocatory movements of the needle or the cam cylinder. On modern fine-gauge, high-speed, circular knitting machines for making ladies' hosiery, only the sheerest yarns are used. The resulting exacting conditions tend to slow down production and to decrease the speed of the machine. These factors cause an increase in cost, while the needs of the times are increased production and lower costs.

According to my invention, the needs of the times are met by a basic reselection and rearrangement of the fundamental parts of the circular knitting machine, so that for the first time, an entire stocking can be knit on a multi-feed basis, starting from the bare needles, making an automatic inturned welt and making the heel and toe with gussets. Where I speak of gusset heels and toes, I refer to heels and toes in which some segments are united by a single-sided suture. One of the difficulties in multi-feed knitting throughout is the necessity for changing yarns. In knitting fine-gauge hosiery it is essential to change yarns. For example, it is desirable to use relatively heavy yarns in the welt, heel and toe, and to use relatively light yarns in the leg and instep. The difficulty is much increased when it is desired to make reciprocatory knitting by multi-feed. It should be understood that my invention is useful not only when making circular knit hosiery on the ordinary machine with a single cylinder or in multiple or inverted cylinder machines, but also when making a stocking of split foot fabric. While the invention will be described in an embodiment where the needle cylinder revolves, it should be understood that many of its features are equally applicable to circular machines with revolving cam cylinders.

It is characteristic of the multi-feed circular knitting machines made in accordance with my invention that they contain a movable raise cam adjacent to one of the center stitch cams adapted to raise needles going under that center stitch cam in order that they may knit at a side stitch cam and that the raise cam is withdrawn during the making of the welt of the stocking in order that some or all of the needles may temporarily take a non-knitting path at at least one center stitch cam. It will be noted that this makes it possible for the cams to remain stationary

2

and unchanged during the make-up of the stocking.

Machines made in accordance with my invention may have a novel juxtaposition and shaping of needle and sinker cams and throat plates which, in cooperation with the movable raise cam, make it possible to knit multi-feed in rotary and reciprocatory knitting in integral succession throughout. In the embodiment shown and described, the machines are adapted to make an entire stocking multi-feed starting up from the bare needles, making an automatic inturned welt and gusset heel and toe with yarn changes.

15 In the drawings:

Figure 1 is a developed view of certain parts of a Scott & Williams machine adapted to make two-feed ladies' hosiery according to my invention, including the throat plates and the needle and pattern jack butt paths. The cams shown in dotted lines are movable;

Figure 2 is a developed view of the needle cam ring and throat plates of Fig. 1, showing the adjustment of the parts when the machine is starting up from the bare needles during the half revolution before the yarns have started to knit, the arrow indicating the direction of movement of the needles;

Figure 3 is another developed view of the same cam ring, showing the relations of the parts during the first three and one-half revolutions after yarn begins to be fed (i. e., the make-up), the arrow indicating the direction of movement of the needles;

Figures 4, 5 and 6 are similar views showing the relation of the parts after the make-up; during the welt and leg; and during transfer, respectively;

Figure 7 is a plan view of the transfer jack dial, dial make-up and transfer cams adapted to cooperate with the cams of Figs. 1 to 6.

Figure 8 is a perspective phantom view of the fabric resulting from Figs. 2 to 6 during welt transfer;

Figure 9 is an inverted plan view of the sinker cap carrying the sinker retracting cams used in connection with the needle cams shown in Fig. 1;

Figure 10 is a view in vertical sections of the inverted sinker cap of Fig. 8, taken on the line 10—10 of that figure;

Figures 11 and 12 are views in side elevation of a sinker, needle and fabric; Fig. 11 showing them when the needle is riding over the hump on the top center cam in Fig. 1 with the sinker retracted; and Fig. 12 showing them after the

needle has been lowered again by the dropper levelling cam;

Figure 13 is a plan view of the transfer jack dial of my machine showing some jack butts and the special slackening cam for the second throat plate in action during make-up, the single-headed arrow showing the direction of movement of the transfer jacks and also the direction of movement of the floating ring which moves the special slackening cam into action;

Figure 14 is a view in perspective of the sinker cap and dial showing the parts for moving the special slackening cam of Fig. 13. The parts are in the same position as in Fig. 13;

Figure 15 is a perspective view of the bedplate of my novel machine, showing the connections from the pattern chain to a special sinker slackening cam and to the switch cams for the needles;

Figure 16 is a partial view of the two controls from the main pattern drum of my machine for the connections of Fig. 15;

Figure 17 is a view in elevation of tripping means for the loop slackening means, this being controlled from the crank shaft of the machine;

Figure 18 is a developed view of the needle butts, knitting cams and part of the sinker cam cap of the needle of Fig. 1, the parts being shown on the last rotary or forward movement of the needle cylinder before beginning reciprocatory knitting to make the toe, as indicated by the arrow, the first of the group of inactive needles raised by the switch cam being shown rising over the hump on the center stitch cam and raising the fabric above the nebs of the adjacent sinkers;

Figure 19 is a partial view similar to Fig. 18, showing only part of the knitting cams and needles, the needles moving on a forward stroke after reciprocatory knitting has commenced, the two leading active needles being shown in the act of rising out of action on a narrowing or up-pick before knitting;

Figure 20 is a view similar to Fig. 19, taken while the needles are moving in the reverse direction, as indicated by the arrow;

Figure 21 is a view similar to Fig. 18 taken while the needles are moving in the reverse direction, as indicated by the arrow, showing the first needles of the inactive group passing above the hump.

Figure 22 is a developed view of the cam ring, throat plates and needle butts of the same machine, showing the path of the needles on the first stroke in reciprocatory knitting where the dropper pick is in action, the arrow showing the direction of movement of the needles;

Figures 23 to 26 are diagrammatic views looking from the inside of the needle cylinder of fabric being formed on the needles during reciprocatory knitting on my two-feed machine where the end needles are raised in pairs producing tie-across yarns. The figures show the making of four successive courses. Fig. 23 shows the fabric after a stroke of the needles in the counter-clockwise or rotary direction, with needles N¹, N² raised out of action by the up-picks on the next or reverse stroke after knitting at both feeds (see arrow); Fig. 24 shows the condition of the fabric and needles after knitting at the left-hand feed on the reverse stroke; Fig. 25 shows the conditions after knitting at both feeds on this stroke with the tie-across yarns appearing opposite needles N¹, N²; and Fig. 26 shows the situation

after one feed has knit on the next forward or rotary stroke;

Figure 27 is a perspective view of the mechanism on the bedplate of the machine for changing the rate of picking needles out of action from two needles to one needle, or vice versa;

Figure 28 is a detail view in perspective of an up-pick post such as used in Fig. 27;

Figure 29 is a perspective view similar to Fig. 28 but of a modified make-up in accordance with my invention in which the transfer jacks are not projected until the fifth course. The dotted outline indicates a welt presser;

Figure 30 is a diagram showing in solid lines 15 the angles of the yarns from the two throat plates at the end of an oscillation. The dotted lines indicate the angles of the yarns while the active needles are drawing yarn at both feeds and the dot-and-dash line the angles of the 20 yarns when drawing from the first feed has stopped at that feed and is about to stop at the second feed;

Figure 31 is a perspective view of a throat plate and a needle being picked up, showing the latch 25 riding above the bevel of the throat plate;

Figure 32 is a perspective view of a throat plate from a different angle showing the needle of Fig. 31 after it has passed beyond the throat plate and its latch is in contact with the usual latch 30 opener;

Figure 33 is a skeleton side elevation of a throat plate showing a depending lip or latch guard while

Fig. 34 is a diagram of a needle arrangement 35 in connection with which the invention will be described.

For the last half century of the circular knitting machine art, the most valuable space on the machine has been the circle represented by the 40 periphery of the needle cylinder. It is only around this circle that the needle movements can be affected and in that 360° must be placed everything directly affecting the needles or sinkers. Some inventions are primarily concerned 45 with the interconnecting of the connections for the parts directly affecting these knitting elements, and such inventions have an interesting cyclic history. However, the present invention concerns a quite radical rearrangement and 50 manipulation of the elements right at the periphery, and in that sense it is a fundamental invention.

General construction

55 The invention will be shown and described embodied in the well-known Scott & Williams model K circular hosiery machine for making ladies' hosiery. That machine has a revolving 60 needle cylinder with independent latch needles and independent sinkers with stitch-holding nebs, as well as transfer jacks. This machine is adapted to start up from the bare needles making a selvedge and to make an automatic in- 65 turned welt and also to knit in both rotary and reciprocatory movements in the making of a stocking. Characteristically, the machine knits only one course per revolution of the machine, which, of course, is a great limitation on the 70 amount of fabric that can be manufactured by the machine in a given time. Many efforts have been made heretofore to increase the production by incorporating two or more feeds in the machine and using them during rotary knitting. 75 Efforts have also been made recently to build a

multi-feed machine for ladies' hosiery in which a multiplicity of feeds are used during reciprocatory knitting, but in no instance of which I am aware has a circular machine been designed in which a lady's stocking could be knit multi-feed throughout.

I have been able to achieve this and yet so arrange and shape the parts that the changing of yarns by pivoted fingers in throat plates can be obtained. I have shown only two such fingers in each throat plate in the drawings but it will be obvious that more can be used if desired. I have been able to do this changing of yarns in spite of the multi-feed reciprocatory knitting in the heel and toe. The changing of yarns is essential in the extremely fine gauges of stockings produced on the modern circular hosiery knitting machine such as 75 gauge etc., and using such very fine yarn as 10 denier nylon.

My machine is further able to start up from the bare needles and to produce an automatic turned welt. Hereafter, where I refer to making up it should be understood that I include not only starting up from the bare needles but also the placing of bights of yarn on transfer jacks as the first stage in the manufacture of automatic turned welts.

Many complications have arisen in designing a machine with these characteristics adapted to run at the high speed of 200 revolutions a minute demanded of modern machines. To accomplish all this on an all-multi-feed basis gives rise to tremendous difficulties. The concatenation of movements arising from the long-established sequence of knitting successive stitches in a wale on the same needle in successive courses at the same point in the machine had to be eradicated completely in order to establish the horizontal course sequence arising from the placing of a multiplicity of knitting points around the needle circle and using them in succession throughout the entire stocking. This destruction of established concatenation has been particularly damaging in the make-up and welt of the stocking, as well as in reciprocatory knitting and in the making of what are called gusset heels and toes. As a result, my invention concerns not only the rearrangement of all the cams affecting the needles, particularly at or near the knitting wave, but also a number of novel arrangements of cams for handling the sinkers and needles to avoid destructive interaction. I provide the necessary new interactions principally during the make-up, welt and reciprocatory knitting. The various changes and the manner in which they coordinate to produce the result above referred to will be set forth after a brief statement of the general construction of the machine.

Many basic parts of the machine are unchanged from the above-mentioned Scott & Williams model K machine, the needle cylinder 260 rotating or reciprocating inside of the cam ring 271 in which the butts of the needles N are controlled (see Fig. 15). The cam ring and needle cylinder are supported in the bedplate and are driven from the standard driving parts. As heretofore, the machine is under the general control of a pattern chain 85 which, in turn, operates a main pattern drum 120 (Figs. 16 and 17). On the surface of the main pattern drum are drum cams 501, 502, 503, etc., whose indications are transmitted by means of the usual thrust bars 461, 462, etc., to the region of the bedplate, whence they are distributed around the needle cylinder 260 and cam ring 271 to cause the nec-

essary changes in manipulations of the knitting elements of the machine. The usual web-holding sinkers S carried on the upper end of the needle cylinder 260 are controlled in their independent radial movement by their butts which contact cams on the inside of the usual sinker cap 300. There are the usual sinker spring bands 740 (Fig. 9). The sinkers have the usual nebs W¹⁰ for holding the fabric down when the needle is rising through the stitch. The transfer jacks T are carried in a dial located axially opposite the upper end of the needle cylinder, this dial including the necessary cams for actuating the transfer jacks in the novel manner hereinafter set forth.

In order to obtain the necessary selection of needles for my novel all-multi-feed knitting of a lady's stocking starting from the bare needles and with the automatic inturned welt, I prefer to employ a pattern jack system such as shown in the U. S. Patent to Ivan W. Grothey No. 1,678,385, dated July 24, 1928. As can be seen in Fig. 1 of the drawings of the present application, this system has pattern jacks 736 whose coming into action is initiated from the main pattern drum, the pattern chain, or a trick wheel, as desired. Short or intermediate jacks 732 located above the pattern jacks are adapted to transmit selections to the needles at appropriate times. Both pattern and short jacks are located in the cylinder slots which contain the needles N themselves. The yarns are shown fed to the needles by pairs of pivoted yarn fingers FR², FR⁴, FL¹, FL³ from two throat plates 560, 561, whose exact construction, location and interaction with the other parts are hereinafter set forth. It should be understood that while I will show and describe my invention embodied in a machine having only two feeds, the invention is equally applicable to a machine having a greater number of feeds or knitting points. Except as specifically limited in the claims or specification, my description should be so understood.

Knitting cam group

The knitting cams in the ordinary revolving needle cylinder independent needle hosiery knitting machine include the stitch and associated cams. They are sometimes described as the "cam box," but they will be referred to in the present specification as the knitting cam group.

Since the knitting wave in the sinkers must bear a trailing relation to the draw-down points of the stitch cams, it is necessary to oscillate the sinker cam cap 300. This oscillation is known as the "throw." In order that this throw may not be greater than necessary, and for other reasons, the stitch cams of my multi-feed machine are kept as close together as possible and the functions of the cams are somewhat changed. I have found it possible to get my cam group in a space only about 50% greater than the length of the cam group of the Scott & Williams model K single-feed automatic inturned welt machine (see Robert W. Scott Patent 1,282,958, dated October 29, 1918). This increase in length is due principally to the necessity for having side raise cams adjacent the double center knitting cam and to the length of the bottom of the double center stitch cam as described in the paragraphs immediately following.

In my novel machine, I provide a plurality of throat plates equal in number to the number of feeds. In the machine shown in the drawings, the so-called auxiliary throat plate 560 appears

at the left side of the figures of the drawings while the regular throat plate 561 is at the right-hand side. Owing in part to the totally different functions of the knitting cams above referred to, the cams bear different relations to the various knitting waves at different times. By this I mean that the stitch-drawing point of a knitting cam always follows or trails the throat plate from which it receives yarn. As a result, the knitting of a multiplicity of courses from those same two throat plates in first the rotary direction and then the reciprocatory or reverse direction requires that the throat plates cooperate with different stitch cam surfaces according to the direction in which the needle cylinder is turning. I therefore provide one more stitch-drawing cam or two more draw-down or stitch-drawing surfaces than there are throat plates in the two-feed mechanism shown. According to my invention there are one-half as many throat plates as there are stitch-drawing surfaces. I so arrange the parts of my machine that the leading stitch-drawing cam on each direction of movement is adapted to act as a clearing cam when it is the leading stitch cam, but draws stitches when it trails. Specifically, in the embodiment shown in the drawings the cam box or group has an intermediate or center stitch cam 50 of unique design, and left and right-end stitch cams 360 and 361 associated therewith, one on either side. This cam 50 is a double one sloping downwardly toward the center from each side. The two slopes 51, 52 are both at about 45° from the horizontal and each slope constitutes an operating or stitch-drawing face. In the example to be described the faces happen to be in fixed radial relation to each other though this is not essential to my invention. These two cam or stitch-drawing surfaces 51, 52 do not meet at the bottom of the cam but each terminates at a separate point 53 or 54. The two points are separated from each other a distance equal approximately to say the width of seven or eight needles as they are mounted in the needle cylinder. For example, in a 400-needle, 3 3/4" cylinder machine, these two points would be approximately 1/4 of an inch apart. In the stitch cam of the ordinary single-feed Scott & Williams model K machine, the back face of the cam, i. e., the raising side, is sloped only about 23° from the horizontal. This gives time for the sinkers to be reinserted after the draw-down point to hold the stitches down by means of the nebs of the sinkers before the friction on the rising needles can force the fabric above the nebs of the sinkers. However, in the new double stitch cam both those sloping surfaces must be used as stitch-drawing surfaces, so each face is of necessity close to 45° from the horizontal. Since with the double stitch cam the rising face of necessity is close to 45° from the horizontal, it follows that the needles rise faster than in a single-feed machine, and "unhooking" of the stitches sometimes occurs. The separation of the two points 53, 54 relieves this by giving the sinkers time to come in and hold the stitches down before they get above the nebs. With these separated points the first point met acts as the draw-down point and the second point met acts as the knocking-over point. It will be noted that the second point is located after the knitting has left the "robbing" area, which is normally considered as existing immediately after the draw point. The relief on the bottom of the main stitch cam between the two points 53 and

54 is a further development of the high-speed, fine-gauge art. It has been found that in knitting fine gauges at high speed with fine yarns, any infinitesimal increase downwardly between the two points might cause cutting of the yarn. The bottom of the cam has, therefore, been shown relieved between the two points. In order to be sure the needles do not by any chance fail to take advantage of this relief, a hump 55 has been put on the bottom center cam 56 directly underneath the double-pointed stitch cam so that the needles necessarily have to give some relief to the yarn. It will be noted that the needles, in passing under the second point after a slight relief, bring the stitches back to the draw-point level momentarily, tending to make uniform again any irregularities which may have occurred since the first draw point was passed. The double stitch cam 50 also has shoulders 57, 58 on each side above the stitch-drawing faces 51, 52 which serve as a check or cover cam when the needles are rising. This prevents the needles jumping over the next stitch cam.

One of the great difficulties in starting the make-up from the bare needles in fine-gauge, modern machines making ladies' hosiery with an automatic inturned welt arises from the high speed of the machine. Other difficulties tied in to this are the necessity for special sinker pressures at special times on special stitches and the necessity for the utmost simplicity in the movements of the parts which control the needles and sinkers. I have invented a combination of parts which are concatenated with the other requirements of the make-up and welt in the simplest possible way and which actually simplify the knitting manipulations as compared to the old single-feed make-up. I will describe each of these features separately.

Make-up cams

It is of the greatest importance in high-speed knitting that the knitting cams be undisturbed throughout the make-up. I have also found it to be essential that the motions of the cams affecting the needles be simplified. As one element in this picture, the following should be noted with regard to the right-hand feed or throat plate 561 and the left-hand feed or throat plate 560. The make-up and welt are produced while the machine is turning in a rotary or forward direction, i. e., counter-clockwise. Thus in Fig. 1 the needles are moving from right to left, which is in the rotary direction. At this time the right-hand throat plate 561 is feeding yarn in a trailing manner to the needles at the main double stitch cam 50 while the left-hand throat plate 560 is feeding its yarn in a trailing manner to the left-hand stitch cam 360. On forward movements, the right-hand stitch cam 361 acts as a clearing cam and to bring needles to the double stitch cam at two levels. I so arrange the other parts of the machine that throughout the entire start-up and also the make-up, the machine will knit at the right-hand or first throat plate 561. Also the transfer jacks will take their bights of yarn at this feed. At the left-hand throat plate 560 all the needles will knit throughout the entire make-up and welt-knitting operation. There is absolutely no movement of the three knitting cams during the start-up or make-up or the making of the welt. This is of great advantage.

75 It is important that the machine be able to knit

multi-feed throughout the entire stocking. This, coupled with the desirability of putting an automatic welt on the stocking and doing it without changing the stitch cam adjustment, makes a complex problem because of the necessity for knitting in a reciprocatory manner as well as rotary. My solution is highly satisfactory in operation and comparatively simple. In the first place I arrange my means for making the special needle selection during rotary knitting at one feed while allowing other feeds to knit multi-feed. For this purpose selected needles take a non-knitting path at the selected feed. In the particular embodiment shown this involves permitting needles approaching the double stitch cam 18 in the forward direction to do so at two levels.

For this purpose I provide a raise cam which is movable. Two raise cams 352 and 353 are shown at the bottom of the double cam 50—one on each side of it. For the embodiment shown I use the right-hand raise cam 353, namely, the one between the double cam and the leading stitch cam 361 in the forward direction. By retracting this raise cam, needles can safely pass under the stitch cam 361 and the machine start up multi-feed from the bare needles or make a turned welt multi-feed.

I will now describe one set of parts which make it possible to cause the dividing of the needles before the main double stitch cam 50 during the make-up and the welt. Referring to Fig. 1 of the drawings, it will be noted that when the needles approach the knitting cam group at the normal level 30 they ride up the upper face of the right-hand stitch cam 361. Thus they are cleared preparatory to taking yarn and riding down the right-hand operating face 51 of the double stitch cam 50. When it is desired to divide the needles for the start-up or welt, it is merely necessary to insert a dividing cam 382 located just in advance of the right-hand stitch cam 361. Operating by butt selection the cam can direct alternate needles to the down-face of the right-hand stitch cam which will guide them under the cam so that they neither clear nor take yarn. On continued rotation of the needle cylinder they will meet the remaining needles again at the point 53 at the bottom of the operating face 51 of the double stitch cam 50. It will now be seen that while each needle makes a stitch in every second course, i. e., at the second feed, every second wale has a float of yarn rather than a stitch made at the first feed. I take advantage of these facts in two ways. In the first place, I use them for a non-ravelling start-up. In the second place, I use them to assist in the rest of the make-up. This is done by using them to provide the bights of yarn for the inturned welt. By concentrating all these activities in advance of the first or right-hand knitting point, I find it possible to get the necessary manipulations of the transfer jacks without in any way affecting the length of the cam box or disturbing the length of stitch drawn at either feed. This leaves the machine in a good position to take care of the special stitch tension adjustments necessary in connection with the sinkers at these particular stages of the knitting—all as will be hereinafter described. Furthermore, it leaves the machine in a good position to permit transfer of the bights of yarn back to the needles when turning the welt.

By the preferred construction now to be described, the function of the dividing cam 382 can be simplified. This preferred embodiment pro-

vides greater flexibility in the choice of the needles to be divided and also moves the selection of needles even further from the knitting cams. At this particular stage of the knitting the needles are approaching the knitting cams at the normal level 30. With this preferred arrangement of cams the first movement of needles occurs some distance before the dividing cam 382 is reached. It consists of a raising of selected needles to a level somewhat higher than the normal level 30. This is obtained by use of a pattern jack and short jack selection made by a trick wheel such as shown in the Ivan W. Grothey patent above referred to, or any other pattern jack means. It is also possible to select jacks from the main pattern drum 120 by having a thrust rod control the selector lever. This lever selects the pattern jacks which are not to ride up the raising cam 741. Referring to Fig. 1 of the present application, pattern jacks 736 not selected by the selector lever (not shown) raise every second needle. This action is caused in the first instance by a pattern jack raising cam 741 shown in the lower right-hand corner of the figure. This raises every jack not pushed back out of its path by the selector lever. These jacks in turn raise the short jacks 732 and the corresponding needles N.

At the upper end of the pattern jacks is an upwardly facing shoulder 729 and as the pattern jacks reach the top of the raising cam 741, the shoulders on the upper ends of the jacks engage against the lower descending face 742 of the special separating cam 743 located at a point just after the raising cam 741. This separating cam 743 has a rising face 744 joining the upper end of the lowering face 742 and owing to the fact that the shoulders 729 on the upper ends of the pattern jacks are slightly below the lower ends of the short jacks, the butts of the short jacks 732 engage against the rising face 744 of the separating cam and continue their ascent. The pattern jacks 736 riding down the lowering face 742 of the separator cam are returned to their original level for subsequent reselection.

When the short jacks 732 reach the top of the rising face 744 of the separator cam, they meet the short jack lowering cam 746 which draws them down away from their needles. At their maximum height, however, the short jacks have raised the needles to a level where their butts are just above the right-hand stitch cam 361. I have found that the dividing of the needles for the start-up and throughout the make-up in its entirety can all be easily initiated by this pattern jack selection. With this arrangement the only function of the dividing cam 382 is to lower such needles as were not raised by pattern jack selection from the normal level 30 to a point where they will pass under the right-hand stitch cam 361. This set-up of the pattern jack selection may be controlled from the main pattern drum 120. Since the main pattern drum is customarily advanced once every four revolutions of the needle cylinder when called for by lugs on the pattern chain, it follows that the selection can be kept up for four revolutions of the machine or any multiple thereof, with great ease. In fact, it is convenient at one stage of the knitting of the welt to let all of the needles be raised by the pattern jacks (see Fig. 4). This can be done conveniently from a pattern drum control of the pattern jack selection by holding the selector lever out of action so that all jacks ride up cam 741.

In Fig. 8 I have shown the laying of the bights of yarn on the transfer jacks T taking place at the second revolution of the machine. It is at this time that the transfer jacks T are projected by a cam 297 (Figs. 7 and 13). When it comes time for the transfer jacks to be projected again to give their bights of yarn back to the needles, they are projected by a transfer projecting cam 296 shown in the same figures. In both instances the return of the transfer jacks to their radially inward position clear of the needles is caused by other cam surfaces in any usual manner. It is while these transfer jacks T are projected by the make-up projecting cam 297 that the needles are passing down through the knitting wave at the double stitch cam operating surface 51 for the second time. Therefore when the transfer jacks are retracted the bights of yarn are held until returned to the needles at the transfer. I prefer to have the dividing cam 382 inserted before the feeding of yarn begins—a matter of say half a course (Fig. 2). As a result, after seven courses of the make-up have been completed, the turning of the main pattern drum provides an opportunity to withdraw the dividing cam 382 from the path of the needles, thus allowing all the needles to knit at both feeds thereafter. The condition of the cams and the paths of the needle butts after this change has occurred is as shown in Fig. 5.

When transferring the bights of yarn from the transfer jacks back to the needles it is necessary to project the jacks over the desired needles while the latter are low so that the needles thereafter can be raised through the jacks. For this purpose I have a cam 23 located at a point shortly after the double knitting wave to lower all the needles from the normal level 30 to the low level C for transfer. When thus lowered by the special cam 23 , the needles remain at the low level until they meet an upstanding projecting cam 41 in the main cam path which raises back to the normal level 30 all needle butts that meet it at the low level C . This projecting cam 41 is located at a point intermediate the point of division of the make-up and the right-hand stitch cam 361 . Actually only every second needle lowered to the low level C by cam 23 will reach the levelling cam 41 because when the needles pass the division point for make-up they also pass the division point for transferring. In other words, the operation of pattern jack selecting which is used for both make-up and transfer will take every other needle from the low level C up past the normal level 30 to the clear level. Such needles will pass over the top of the right-hand stitch cam 361 . It is between the time that these pattern jack raised needles reach the clear level and the time the remaining needles reach that clear level that the transfer jacks are projected. The point where the needles will begin to be projected through the jacks is at cam 41 . The needles which went to the clear level by virtue of being raised by the pattern jacks are the ones between which the transfer jacks are projected. When the transfer jacks are retracted they leave the bights of yarn on the needles.

Transfer jack tension relief

Turning now to the matter of tensioning of the fabric at various points in the make-up, it is noted that on the ordinary single-feed model K Scott & Williams machines it has been necessary to knit a second course on alternate needles after

the course where the bights of yarn are placed on the transfer jacks, in order not to put too much strain on the loops held by the transfer jacks. I knit on all the needles at the second feed during the make-up. I therefore have provided tension-relieving means at the second feed for the bights of yarn on the transfer jacks that were taken at the first feed. This construction is shown in Figs. 13 and 14. A radially movable cam 27 shown at the left-hand part of Fig. 13 is adapted to press the jacks radially outward. This projection of the jacks relieves the strain on the fabric at that point. This cam 27 is pivotally mounted on the dial and is moved from its operative to its inoperative position by a floating ring 28 which turns about the center of the dial. The direction of movement of the floating ring indicated by the arrow in Fig. 13 shows the direction of movement thereof which brings the cam to its operating position. The connections from the floating ring to the cam on the main pattern drum 120 are shown in Fig. 14. There is a pin 29 fastened to an outer wing of the ring 28 . This pin extends through the upper side of the dial cap 36 and is connected to a lever 31 pivoted on the latch ring. The other end of this pivoted lever 31 is connected by a link 312 to a bell crank lever 311 which in turn is operated by a thrust bar 461 in such manner that when the thrust rod rides up onto a cam on the main pattern drum the floating ring is turned in the direction of the arrow of Fig. 13 to bring the cam into action. An extra arm 35 acts as a stop arm to prevent the lever 31 being out of position to receive pin 29 after the dial cap 36 has been removed and is being replaced.

With the arrangement above described in which all the needles knit at the second feed immediately after the transfer jacks get their bights of yarn, there is no excess strain on the bights of yarn in the transfer jacks due to all of the needles knitting.

Multi-feed reciprocity

Much of the difficulty in constructing my new machine arose in connection with reciprocatory knitting. I found it necessary to increase the oscillation of the sinker cap in addition to the features hereinafter set forth.

Owing to the increased length of the knitting cam group and the multiplicity of feeds there was a tendency of the yarns to catch under the nebs W^{10} of the sinkers during reciprocatory knitting. At the end of a stroke or movement in either direction the yarn tended to catch under the nebs of sinkers adjacent idle needles. In certain specific instances there is also the difficulty that the sinkers push too hard on the yarns and breakage of yarn occurs. To avoid these troubles I raise, with relation to the sinkers, the yarn lying between the last needles to knit and the throat plates. This is accomplished partly by raising stitches and partly by the special bevel on the throat plate. One way in which I do this is by raising the stitches temporarily above the nebs of the sinkers in a certain manner. This lifts the lower ends of the yarn coming from the throat plates. I prefer to do this at the double stitch cam 50 . At the top of this cam it will be noted I have provided a raised portion or hump which forms two shoulders or cams 38 and 39 facing in opposite directions. The cams $38, 39$ can be seen in Fig. 1. The dimensions of the stitch cam are such that when a needle butt has ridden up cam 38 or 39 the needle is at its highest

level. When it rides up the cam the friction of the stitch on the needle shank will raise the stitch with it unless prevented by the nebs W^{10} of the adjacent sinkers. At this point I provide the usual means to retract the sinkers momentarily which frees the stitches to rise above the nebs. The hump of the double stitch cam is about $\frac{3}{2}$ " high so a stitch cannot be raised more than this controlled amount at this point.

The sinker retracting means can be seen in Figs. 9, 10, 18 and 21. There are two basic sinker retracting cams **301** and **302** in the sinker cap **300**. These may be fixed cams, if desired, and I have so shown them. They are so located that when the needle cylinder is turning in one direction one of them will be opposite the cam **38** or **39** on the double stitch cam—namely, the leading end of the hump, and on the other direction of movement of the needle cylinder the other sinker cam will be opposite the other end of the hump. These relative positions can be seen in Figs. 18 and 21. The cams or humps **38**, **39** are located so as to act while the sinkers are withdrawn. It is only the idle needles whose stitches I thus place above the nebs W^{10} of the sinkers.

One stage of the knitting at which the raising of needles over the hump is useful is shown in Fig. 18. Here the machine is on the last part of its rotary movement before going into reciprocation for the toe, i. e. what is called the last forward stroke going into the toe. This view shows the butts of the first of the inactive needles riding up the hump cam **38** on the top of the double center stitch cam **50**. Since the sinker retracting cam **302** is in position to cooperate with the hump the loops on the inactive needles will be raised above the throats of the adjacent sinkers not over $\frac{3}{2}$ of an inch. It is the last active needle, i. e., the needle ahead of the leading inactive needle, to which the yarn from the throat plate is attached. By raising the fabric on the leading inactive needle above the nebs of the adjacent sinkers, the yarn coming from the last active needle is supported at a higher level than otherwise, as I will now explain. It should be noted that the moment of danger for the yarn extending from the last needle to knit to the throat plate is toward the end of the stroke on which the stitches on those needles were knit and before the needle is picked up out of action. Thus the needle to which the yarn is attached is not actually picked up out of action until after the danger point has been passed. When the last active needle has knit at the first throat plate **560** and passed it, and especially when it reaches the second feed point, the yarn from the first feed has been pulled out to a fairly low angle as shown by the dot-and-dash line in Fig. 30. When the machine comes to the end of its rotary movement both yarns are out at low angles, as shown by the solid lines in Fig. 30. This brings them dangerously near the sinker nebs. While the machine is equipped with the usual yarn spring take-ups to retrieve the yarn during reciprocatory knitting, it is very difficult to retrieve yarns if the yarns have been allowed to go under the sinker nebs and be corrugated between the needles by the sinkers. Sometimes this produces a loop which is not retrieved or the yarn misses the first needle, causing a "throw out." The elevation of the fabric at the last inactive needle as above described provides a ledge to lift the yarn above the nebs of the sinkers. This prevents the yarn catching in the throats

of the sinkers and avoids all the troubles mentioned.

The situation on all subsequent strokes in the forward direction of movement is slightly different and is shown in Fig. 19. On these subsequent strokes in the forward direction the needle or needles raised out of action have the yarns leading from the throat plates attached to them because the preceding knitting was in the other direction and the last stitches were knit on that needle or needles. Assuming that two needles are picked up by an up-pick **650** they ride up the cam **38** on the double center cam and thereby put their loops above the nebs of the sinkers, taking with them the yarns coming from the two throat plates. The yarns then float across the front of the two newly raised needles to knit into the needle wale adjacent to them. This creates "tie-across" loops of yarn on the two inactive needles. These tie-across loops are held high enough to clear the sinker nebs. If the tie-across yarns had caught under the sinker nebs they might be cut or broken. The manner in which my invention functions to take care of the situation at the leading end of the active segment of needles on reverse strokes in either the heel or toe of a stocking is shown in Figs. 20 and 21 of the drawings. The needles picked up have the yarns leading from the throat plates attached to them.

Gusset toe controls

In making certain types of heels and toes the needles involved in the making of successive segments of fabric vary. For example in making the gussets composing a heel such as shown in the Sheppard U. S. Patent 2,388,649, dated November 6, 1945, in two successive narrowed gussets different maximum quantities of needles are involved. However, it should be understood that this is only one use of the special sinker retracting cam **391** and the switch cams **415** and **419**. These cams are equally useful in making any single-sided gusset. In the case of a single-sided suture, the number of needles used after the switching down and up of the needles may be the same as before or not, as desired. Thus it should be understood that where in the specification I speak of "a gusset toe or heel," I refer to one in which pieces of fabric are joined by a single-sided suture, as distinguished from a double-sided suture. The customary way of getting the selection of needles for the second gusset in the heel is to pull all the inactive needles down by means of a switch draw-down cam **415** and immediately thereafter to raise a different group of needles by a switch raising cam **419** before the needles pass through the knitting wave. Thus the different actions of the switch draw-down and the switch raising cam result in a new needle selection.

These changes occur on the forward or rotary stroke of the machine and there are two such occasions in the making of the heel of a stocking such as shown in the above-mentioned Sheppard Patent No. 2,388,649. If something were not done with regard to the relation of the stitches on the needles and the sinkers, trouble would occur at these two points in the fabric because the loops on needles that were idle are still above the nebs W^{10} of the sinkers as the needles are moved by these switch cams **415** and **419**. The trouble would be the needles rise so far in going up the switch raising cam **419** that they would carry their stitches too high. This could cause breaks

in the fabric due to the strain between the extremely high needles and the low needles and also might interfere with the proper functioning of the latches on the high needles. The latches on the high inactive needles are open, of course, and the fabric should at no time interfere to the extent of closing those latches. The fabric is high on the needles and it is possible for the stitches to exert pressure on the latches when the needles are lowered. Also the latches might be closed on inactive needles when passing the throat plates without gap closure protection.

I find that by putting in a special sinker retracting cam 391 operated in conjunction with the switch draw-down cam 415, all the stitches will be brought below the nebs by the time the fabric and needles have reached the bottom of the switch draw-down cam 415. Thereafter as the needles rise up the switch raising cam 419 it makes no difference how far they rise because the sinkers have passed beyond their cam 391 and the fabric is held down by the nebs. If it is desired to get a new selection of needles for a second gusset in the toe instead of using switch cams 415 and 419 it would be necessary to use switch cams 32 and 33 to shift the needles down because the machine would be knitting on the long butt side of the needle circle. Cams 32 and 33 take separate groups of medium butt needles. If subsequent operations required raising needles additional sinker retracting cams could be placed with cams 32 and 33.

The switch draw-down cam 415 and the movable sinker retracting cam 391 just described are controlled together by the mechanism shown in Figs. 9, 15 and 16. The primary control is by a drum cam 501 on the main pattern drum 120 acting through a bell crank lever 399 shown in Fig. 16. At the upper end of this bell crank lever is a link 397 connecting the bell crank lever to a control lever 398 pivotally mounted on a vertical axis on the bedplate of the machine. The other end of this control lever 398 inserts and removes the switch draw-down cam 415 and the switch raising cam 419.

In circular knitting machines of the general type being described, the main pattern drum 120 is racked forward only intermittently as dictated by the pattern chain. It so happens that there is no pattern drum movement occurring at the time it is desired to insert the switch draw-down cam 415 on the run-down stroke in the heel as the selection of needles is being changed for the second gusset. I have therefore devised mechanism actuated from the pattern chain 85 itself which coordinates with the connection to the main pattern drum just described, and with additional connections which I will now describe, to cause the switch cam 415 to be operated at the desired time. These means operate the sinker retracting cam 391 during the making of the heel and avoid undesirable movements of any of the parts or of these cams at other times. The pattern chain control originates with a side lug 851 on the pattern chain and a pivoted reader arm 392 lying in its path. This reader arm is connected to a vertical link 393 which in turn transmits motion to a lever 394 pivoted on an adjacent stationary part of the machine. These connections are such that when the reader arm 392 rides up onto the side lug 851 on the pattern chain, the far end of the pivoted lever 394 will be lowered. This far end is connected to a safety linkage that transmits the vertical movements of the end of the lever 394 to a bell crank lever 395 mounted on

the periphery of the bedplate of the machine. To the other end of this bell crank lever 395 is fastened a wire or rod 396 which connects to the link 397 and thence to the lever 398. The connection between the bell crank lever 395 on the edge of the bedplate and the rod 396 may be a lost motion connection and I have shown it of this type. The connection of the parts thus far described is such that when the lug 851 comes under the reader arm 392 and raises it, the rod 396 moves the link 397, and lever 398, thus causing insertion of the switch draw-down cam 415. If it is desired to keep the switch draw-down cam 415 in action after the lug 851 of the pattern chain has passed from under the reader arm 392, then the pattern drum cam 501 on the surface of the main pattern drum can be caused to come under the arm depending from the bell crank lever 399 before the lug passes from under the reader arm.

To actuate the special movable sinker retracting cam 391 in cooperation with these parts there is an arm 383 fixedly attached to the bell crank lever 395 on the periphery of the bed-plate. At the upper end of this arm 383 is a lost-motion connecting rod 385 going to a lever 384 carried on the upper end of the post carrying the control lever 398 for the switch draw-down cam 415. This lever 384 extends toward the sinker cap 300 and has upstanding from its end a pin 386 which operates the sinker cam 391 by means of a flat lever 387 pivoted on the sinker cap at 388 and a pin 389 in the cam. There is a tension spring 383a attached to the arm 383 tending to pull it to the right as shown in Figure 15. These parts are so arranged that when the switch draw-down cam 415 is pushed into action from the side lug 851 on the pattern chain, the movable sinker retracting cam 391 will also be pushed into action.

The safety linkage, which connects the lever 394 to the bell crank lever 395 on the edge of the bedplate has a special function. One of the objects of this linkage and its control elements is to insure that the connection from the pattern chain to the switch cam 415 and sinker retracting cam 391 is effective only at times when it is desired to operate from the chain and that there is no possibility of it operating at other times. To this end the linkage and its controls are so arranged that no lug on the pattern chain can operate the switch cam and sinker retracting cam except when a special pattern drum cam 502 permits it. The safety linkage has two vertical bars 510, 511 slidably attached to one another, bar 510 being attached at its lower end to the horizontal lever 394 and bar 511 being attached at its upper end to one end of the bell crank lever 395 carried on the edge of the bedplate. This sliding relation is obtained by slots and screws in well-known manner. When these two bars are held in their contracted relation, the indications of the side lug 851 on the pattern chain are transmitted to the bell crank lever 395. To hold the two bars in their contracted relation there is a latch 512 and a pin 513. The pin is located on the lower bar 510 and lies in a slot in the upper bar 511. The latch 512 is carried on the upper bar 511 by a screw 514. When the latch 512 underlies the pin 513 the bars are held in their contracted position. In this position the slots in bar 511 permit it to be lowered slightly without disturbing bar 510 thus permitting free entry and exit of the latch 512. To dislodge the latch 512 from the pin 513 and allow the two bars 510 and 511 to slide freely with respect to each other there is a wire 515 extend-

ing from the lower end of the latch 512 to a pin 516a in the upper arm of the bell crank lever 516 located adjacent to the pattern drum. This is preferably on the same center as the bell crank lever 399 which operates the control lever 398 for the switch draw-down cam 415. The lower end of this bell crank lever 516 lies in the path of the drum cam 502 above referred to (Fig. 16). The connection between the rod 515 and the bell crank lever 516 involves a compression spring 517 on the rod 515 so that the bell crank lever can ride up on its cam and permit the latch 512 to lock the bars 510, 511 in their contracted position when the bars next move to that position. As the machine goes into the heel the latch 512 is engaged under the pin 513 and these parts stay latched all during the making of the heel. The first preliminary move of the main drum coming out of the heel is the time when this latch is disengaged. On the next move of the main pattern drum the needles are taken down by means of movement of the pattern drum actuating the lever 397. On this movement the clutch is so shifted that later when making the toe pocket it will be knit on the opposite side of the fabric from the heel pocket. On the next move of the pattern drum, the yarn is changed going from the heel into the foot.

Before going further in this description I will describe the throat plates 560 and 561 in more detail. These parts are very important to this invention. They each contain pivoted yarn fingers to permit different selections of yarns. In the left-hand throat plate I have shown finger FL^1 and FL^3 while in the right-hand throat plate I have shown FR^2 and FR^4 . It should be understood however that the number of fingers may be changed provided only that there are enough to give different selections for the welt, the leg and the heel and toe.

Picking needles up in multi-feed reciprocation

The changes in picking arrangement caused by picking up the needles in pairs further affects the matter of the yarns being damaged by the sinkers at the beginnings of the oscillations of the needle cylinder in reciprocatory knitting. The fabric conditions are shown in Figs. 23, 24, 25, 26. The picking up of the needles is shown in Figs. 19 and 20.

On the first oscillation or stroke of the making of a heel, the last active needle N^1 of the active group and the adjacent active needle N^2 knit the yarn YR from the right hand feed and then the yarn YL from the left hand feed. This first oscillation is in the forward direction and is the end of the rotary knitting of the leg or foot. They are raised to inactive level by one of the up picks 650 at the start of the following oscillation (Fig. 23). The two adjacent needles N^3 and N^4 in the permanently inactive group in the heel were raised out of action by the switch raising cam 419 before the first stroke just described. On the reverse stroke the yarn YL from the left hand throat plate is knit first (Fig. 24) and then the yarn YR from the right hand throat plate (Fig. 25). On the next forward oscillation the last active needle N^5 and its neighbor on the adjacent end of the active group knit yarn from both feeds and are then raised to inactive position during the following reverse oscillations. In Fig. 26 the arrow indicates the direction in which the knitting is proceeding. The yarn YR is shown just after it has knit on a forward or rotary stroke at the center stitch cam 50

but before the left-hand stitch cam 360 has finished knitting. The yarn knit last at one stroke is the first yarn to be knit in the next stroke at the reversal of direction of movement of the needle cylinder so that throughout the heel or toe the fabric consists of consecutive groups of two courses, each group knit entirely of the same yarn. At each stroke the yarn from each throat plate is knitted by the last active needle which is raised to the inactive level on the following stroke along with its adjacent needle before knitting begins on that stroke. The yarns then float across the front of the two newly raised needles to knit into the needle whale adjacent to them. Thus the last yarn to be knitted by the final active needle above described is the first to be knitted in the following course.

Due to the novel picking just referred to there exists a point between needles N^1 and N^2 where there are bights or floats of yarn floating across two needles picked to the inactive level which is subject to damage by the sinkers when they are pushed in by the sinker side cam. These bights can be described as "tie-across" yarns. The hump on the double center stitch cam 50 which I have described raises these newly picked needles to their final height, frictionally raising their stitches above the nebs of the withdrawn sinkers so that when those sinkers are returned immediately after leaving sinker cam 301 or 302 they will pass under the peculiar tie-across bights of yarn shown in the drawings. Thus it will be seen that, as far as concerns the tie-across yarns, the release of the yarn from the throats W^1 of the sinkers serves an added function. The difficulty with the tie-across yarns is not so much that they themselves are caught by the nebs of the sinkers but that the throats of the sinkers corrugate the yarns between the needles too tightly and the yarns are apt to break. By putting the tie-across yarns above the nebs the pushing in of the sinkers has no effect on the tie-across stitches.

Throat plate bevel

The matter of keeping the yarns coming from the throat plates from catching under the nebs of sinkers in the idle group of needles has still another aspect. When the needle cylinder revolves past the point where active needles are drawing yarn the angle of the yarn running from the throat plate to the last needle to which it is attached begins to grow less. As shown in Fig. 30 as long as the active needles are drawing yarn the yarns from the two throat plates will form angles with the horizontal represented by the two parallel dotted lines. By the time the last active needle reaches the left-hand throat plate 560 the yarn from the right-hand throat plate 561 will lie in the position of the dot and dash line extending from the right-hand throat plate 561 to the active needle below the left-hand throat plate 560. Obviously the trailing yarn from the right-hand throat plate has begun to be vulnerable and the angles of yarns decrease from this moment to the end of the stroke. It should also be noted that at this time the sinkers are being inserted.

I propose to take care of this extra low level of the trailing yarn without disturbing the general set-up by special shaping of the throat plate. For this purpose I slope one end of the edge of the plate upwardly on each of the two plates shown. The end sloped is the one over which the yarn is delivered when the throat plate is the following or trailing one, i. e., the first one reached in that direction of movement. Thus on the left-hand

75

plate 560 the right end 562 is sloped, while on the right-hand throat plate 561 the left end 563 is sloped. If there were three throat plates, both ends of the center plate could be sloped because on both directions of movement the yarn from the center throat plate would be a trailing one. The purpose and effect of this construction is as follows. In the first place it should be noted that the upward slopes on the ends of the throat plate do not come into action until the active needles have passed. After all the active needles have passed both throat plates the yarns will drag further out to the side as the needle cylinder goes out to the end of its oscillation. This lowers the angle of each yarn nearer the horizontal. It will be noted that while the two yarns are tied to the same needle at this stage of the knitting their throat plates are separated. As a result the trailing yarn is at an angle nearer the horizontal than the leading yarn and therefore is lower and nearer to the nebs of the sinkers beside the idle needles than the leading yarn. This difficulty is cured by the slopes 562 and 563 at the trailing end of each throat plate. After the active needles have passed, the yarn at the trailing throat plate rises up the slope, thus automatically tending to equalize the angles of the two yarns and avoiding difficulty with the trailing yarn as distinguished from the leading yarn. The approximate amount the yarn rises at the throat plate is shown by the opposed arrows in Fig. 30. The timing of the operation is such that the yarn is rising up the slope of the throat plate before the sinkers start to come in on the second feed, thus producing an angle so the sinker nebs can get under the yarn. The support given this yarn by the raised stitches on the idled needles also helps this condition. Thus these stitches tend to cam the yarn above the sinker nebs because the stitches themselves are above the sinker nebs. This bevel on the throat plate is one of the features that makes it possible to use throat plates and to obtain yarn changes. This automatic adjustment takes place in both directions of oscillation and establishes and destroys itself at the proper times and at the proper throat plate without any moving of parts. It does not cause any change in the feeding of yarn on either reciprocating or rotary knitting while needles are actually drawing stitches. It is a simple device which acts only at the desired time and place. It is fundamentally useful in multi-feed reciprocating knitting.

Changing up-picking

I have already referred to the fact that the machine is adapted to change the number of needles raised out of action on each stroke, and the construction permitting this is shown in Figs. 27 and 28 of the drawings. The characteristic feature of this mechanism is the picker-positioning slide 651 shown in Fig. 28. According to the position of this slide the up-picks 650 are left at an elevation which will cause either one or two needles to be raised on each oscillation. When the mechanism in Figs. 27 and 28 permits the operating ends of the picks to rest in their lowermost position in the notches in cams 360 and 361, two needles will be raised on each oscillation as shown in Figs. 19 and 20. When held so that the needle butts meet the lower lip first then only one needle will be picked up. This ability to change up-picking is first used during the narrowing operations. The machine is provided with a usual dropper or lowering pick 680 located under the usual dropper levelling cam 416 (Fig. 22). Gen-

erally speaking, when the dropper or widening pick 680 comes into action, the up or raising picks continue to operate but have their adjustment changed by the mechanism in Figs. 27 and 28 to raise only one needle at a time instead of two. Since the widening pick or dropper shown brings three active needles down at each reciprocation, it follows that the increase when both the up-pick and dropper are in action is a net increase of two. The slide 651 which accomplishes this change is controlled by a wire 652 connecting to a plate 653 pivoted on the bedplate of the machine which in turn is linked to a link 654, shaft 655, bell crank lever 656 and thrust bar 463. When the thrust rod rides up on to a pattern drum cam (not shown) the slide moves its position and leaves the pick in its uppermost operating position and from which it will raise the needles only one at a time.

Slack course for looping

It is peculiarly desirable during the making of the loopers rounds in a stocking made on a machine of the type described, that there should be a loose course to facilitate the looping operation. Contrary to previous practice, on this machine the loose course is made on the second course of knitting after the toe. The mechanism for causing this to occur on the second course after the toe is shown in Fig. 17. In the path of a pattern drum cam 503 on the main pattern drum 120 lies a thrust rod 462 extending upwardly through the usual upper comb 453 and lower comb (not shown). There is a side lug 583 on the upper end of the thrust rod 462 and resting on this side lug is the end of a pivoted lever 466. The pivot point 465 of this lever is intermediate its ends and the far end of the lever overlies a pin 364 extending outwardly from the left-hand stitch cam 360. This stitch cam can be slidably carried in the cam cylinder and spring-pressed upwardly so that when the end of the lever overlying the pin extending from the stitch cam pushes the pin downwardly the stitch cam will draw longer stitches than usual until released by the lever 466. When the thrust rod 462 rides up on the pattern drum cam 503, the left-hand stitch cam draws longer stitches. Since we desire only one course of long stitches, and the pattern drum is racked forward only once every four courses, it follows that some means must be provided for pushing the lower end of the thrust rod off the drum cam 503. These means comprise a connection to the main shaft 322 of the machine, as follows. Mounted on the side of thrust rod 462 near its lower end is an arm 461 extending into the path of an end face of a collar 468 on the shaft 322. From the collar a pin 469 projects in line with the arm 461. When the pin comes round into engagement with the arm 461 it pushes the thrust rod 462 off the drum cam 503.

Delayed make-up

In some cases it has been found advisable not to bring the transfer jacks out to take their bights of yarn as soon as the second course of the make-up, as shown in Fig. 8. This is due to the free ends of the yarns which are present at the beginning of the make-up. As shown in Figs. 29 and 8, two yarns are used at each feed, making four in all. If these are especially strong yarns and they happen to whip themselves into the hooks of the transfer jacks, they may form a barrier stretching across a dozen or more jacks. Occasionally such a barrier may force the needles

out of line when the transfer jacks are projected, thus causing trouble. These vagrant yarns should be wiped under the transfer dial and, speaking generally, this can be done by means of an instrument such as a welt presser. A welt presser is shown in dotted lines in Fig. 29 but it should be understood that this dotted line showing is not intended to illustrate the circumferential position of the welt presser. In practice, the ordinary welt presser would be approximately over the lowest point of stitch cam 50. Such normal welt presser can be used to cam the vagrant ends of yarns under the dial in the construction shown in Fig. 29. This is possible because there is an extra revolution between the make-up and the taking of the yarn on the transfer jacks, thus allowing time for the usual welt presser to wipe the yarns and still allow it to come out just prior to the loops being taken on the transfer jacks. In the case of the construction of Fig. 8, in order to wipe the vagrant ends of the yarns under the dial, a second welt presser may be inserted approximately over the dropper widening pick 680 (Fig. 22). As stated the welt presser must be withdrawn before the transfer jacks are projected. To allow ample time for the welt presser to act and retire I find it preferable to postpone the projection of the transfer jacks till the fifth course, as shown in Fig. 29. This delayed make-up is the same as the original form shown in Fig. 8 in that the jacks get yarn from the right-hand throat plate 561 and in that the preceding course at the left-hand throat plate is knit of a single yarn. In both cases the courses preceding that single thread course each has two or more yarns.

In Figs. 30, 31 and 32 I have shown the bevels or sloped edges 562, 563 that serve to raise the yarn first to knit during a reciprocating stroke after the last active needle has passed. Such raising of the yarn is an aid in preventing the yarn from getting into the throats of the sinkers opposite the idle needles, especially as the first of such idle needles pass the sinker withdrawal point at the second feed, a condition which is apt to cause the yarn to be fractured. The bevel or latch-opening angle 565 (Fig. 31) will cause a latch of an idle needle that has become partly closed as it passes the open throat plate to open. The hump 39 on the top of the center stitch cam does not commence to raise a needle or needles lifted by a pick, as shown in Fig. 20, until such needle or needles get past the latch opening angle 565, thus preventing the latch on needles being raised from snapping closed as the needle or needles ride up the hump.

In Fig. 33 is shown another feature which is of great value in making it possible to knit multi-feed. The chisel-shaped lip 584 depends from the edge of each throat plate. The lip is so placed that the needles coming up from the center stitch cam 50 on either side will not have latch trouble if a needle comes up with a partly opened latch. This may occur if there is no stitch on the needle or if there is a broken stitch on the needle. If the latch comes up partly open, the chisel lip 584 will insert itself between the latch and hook and open the latch before it can be damaged against the bottom of the throat plate.

Before beginning the description of the operation of the machine I desire to call attention to the needle arrangement shown in Fig. 34. This shows the arrangement of the needles in the needle cylinder according to the lengths of their

operating butts. The needles in the upper half of the circle all have longer butts than those in the lower half. The middle of the upper semi-circle of needles is occupied by a group of needles with medium long butts (.338). This group is flanked on each side by a somewhat smaller group of needles whose butts are long (.390). These groups may be designated as the first and second .390 butt groups. The ends of the upper semi-circle are occupied by groups of needles whose butts are medium long (.338). These may be designated as the first and last .338 butt groups to distinguish them from the middle .338 butt group. The lower semi-circle with the shorter butts is arranged in a somewhat analogous manner. In the middle is a fairly large group of needles with short butts (.240). Flanking this group on either side is a small group of needles with slightly longer butts (.270). These may be designated as 1st and 2nd .270 butt groups. The ends of the lower semi-circle are occupied by needles with medium short butts (.300). They may be called the 1st and 2nd .300 butt groups.

Operation

The construction of the machine and the effect of the individual needle and sinker movements on the stitches having been set forth, I will now describe the sequence of operations of the preferred embodiment, namely, the construction shown in Figs. 1 to 28 and 30 inclusive.

I will start the description at the point in the cycle of operation in the machine when a stocking has been completed and dropped off the needles. At this moment, all the yarn fingers have been raised out of operation and needle cams which are movable have been taken out of action. This refers to the cams identified as the dividing cam 382, the switch cams 415 and 419 and the right-hand raise cam 353, etc.

The operation of the control mechanism which pressed off the fabric and left the machine in this condition also puts into action the pattern jack selecting means. The selector lever rocking every other pattern jack 736 about its rocking point 728 presses the lower end of the alternate jacks radially inward out of the path of the pattern jack raising cam 741. The intervening pattern jacks thereupon ride up the raising cam 741, taking with them their short jacks 732 and needles. The paths of the butts of the two kinds of jacks are shown in Fig. 1. The pattern jack path is shown by the letters PJ and the short jack path by SJ, these movements corresponding to the description heretofore given.

The movements of the needles can also be seen in Fig. 1.

The paths of the selected needle butts from the time they are picked up for raising by the short jacks until they have passed above the right-hand stitch cam 361 are designated by the letter A.

The needles coming from the press-off reach the point where the pattern jacks are selecting every other needle at the normal level 30. The needles which are raised by their pattern and short jacks, namely, every other needle, are raised from this normal level to a level at which they pass above the right-hand stitch cam 361. This is the upper of the two paths shown at the right-hand side of Fig. 2 of the drawing, and in Fig. 1 this upper path is designated by the reference letter A. The needles moving at the lower level, namely, at the normal level 30, follow a path 78 which in Fig. 1 is indicated by the reference char-

acter B. At the normal level the needle butts just clear the top of a raising or levelling cam 41 which will be hereinafter referred to. They engage the upper or clearing surface of the right-hand or end stitch cam 361 and are raised to clearing level where they join the needles that were selected by the pattern jacks.

After the needles have passed beyond this right-hand or end stitch cam 361 and are all at the same level, they meet the shoulder 57 of the main double stitch cam 50, pass under the shoulder and down the right-hand operating face 51 of the double center stitch cam. They pass under the right-hand point 53 of the double stitch cam, which is acting as a draw point, and are relieved by the hump 55 on the bottom center cam 56. They then pass under the left-hand point 54 at the bottom of the double center stitch cam which is acting as a knocking over point and are raised by the special left-hand side raise cam 352. This raise cam 352 raises the butts sufficiently to cause them to engage the rising face of the usual side cam 354 that brings them up to a clear level. As shown in Fig. 2, the needles establish these paths of travel before any yarn fingers are thrown into action. Then the needles go down through a second knitting wave by passing under the left-hand side stitch cam 360 and back up to the normal level 30.

After the alternate selection of needles of Fig. 2 has been established, the controls of the knitting machine are racked forward to start the make-up.

The first thing that happens is the insertion of the dividing cam 382 located just ahead of the right-hand side stitch cam 361. This directs the oncoming needles not selected by their pattern jacks and therefore moving at the normal level 30 into the path D to pass under the right-hand side of this cam 361. This carries the needles down to the level of the knitting point 53. These are what are termed the low needles in the make-up.

The selected needles, however, continue in the high path A, being drawn down first by the double center stitch cam 50. The waves in the knitting thus established are shown in Fig. 3, the arrow at the top of the figure indicating the direction of travel of the needles.

About half a revolution of the needle cylinder after these paths of travel are established, the yarn fingers are moved into operative position at both the throat plates. Only the selected needles travelling along path A take yarn at the right-hand throat plate 561 and knit at the right-hand feed but all the needles take yarn at the left-hand throat plate 560 and knit at the second feed.

As the division of needles in Fig. 3 is established the two yarn fingers in the left-hand throat plate 560 drop into action so as to feed yarn to the same group of needles where the right-hand throat plate began to feed yarn.

It will be seen that in the first course every other needle is knitting, namely, from the right-hand throat plate 561, while in the second course obtaining yarn from the left-hand throat plate, every needle is knitting. This cycle of knitting continues for three and a half revolutions of the needle cylinder or six full and two partial courses which in the example given constitutes the make-up.

At the beginning of the second revolution of the needle cylinder, the manipulations take place which result in the taking of bights of yarn by the transfer jacks for the automatic inturned

welt. Referring for the moment to Fig. 7, which is a view looking down on the dial of the machine with the transfer jacks T rotating in a counter-clockwise direction, attention is called to the projecting cam 297. This projecting cam 297 in the dial pushes out the transfer jacks T to take bights of yarn from the needles at the right-hand throat plate. The jacks are returned to an intermediate position by a projection in the outer edge of the path in which they travel and by the time the needle cylinder has made one revolution, the projecting cam 297 has been withdrawn and the transfer jacks remain in their intermediate position retaining the bights of yarn on their hooks until it is time to transfer them back to the needles.

As the transfer jacks get their bights of yarn the thrust rod 561 rises turning the floating ring 28 and projecting the relieving cam 27 to the solid line position of Fig. 13. The cam is retracted a few courses later.

After the needles have knit 3½ revolutions of the make-up, the dividing cam 382 is withdrawn ending the needle paths shown in Fig. 3. Thereafter all the needles knit at both feeds during the welt. This is shown in Fig. 5 of the drawing.

If more convenient for the timing of the machine, the needles can all be raised by the pattern jack selecting means to the clear level path A of Fig. 1 for three courses. This is shown in Fig. 4. This may be more convenient since the pattern jack selecting means is put in operation ahead of the make-up dividing cam in order to get started properly and therefore the selecting means normally would come out ahead of the dividing cam. If, for any reason, this is undesirable the lengths of the drum cams on the main pattern drum can be stepped and the difficulty with regard to the dividing cam thus avoided.

After the desired length of welt has been knit, the lowering cam 23 is introduced into the line of needle butts as they have come up to the normal level 30 after the knitting wave at the left-hand feed. This lowering cam 23 carries all needle butts down to a path C which is so low that the hooks of the needles permit projection of the transfer jacks over them. The transfer jacks as usual are only over unselected needles which, for the sake of example, are shown as alternate needles. Before the transfer jacks are projected by the cam 296 shown in Fig. 7, the patterning mechanism has raised every other needle to the clearing height as shown by the path A in Fig. 1. While the needles are at this height, the transfer jacks are brought out by the cam 296 between those elevated needles and over the low alternate needles. This projection of the transfer jacks occurs at a point ahead of cam 41. The low alternate needles which were not selected by the pattern jack mechanism are then projected upwardly by the transfer levelling cam 41.

After the bights of yarn have been transferred from the jacks back to the needles, knitting continues at both throat plates throughout the leg as in Fig. 5. On the last rotation of the needle cylinder in knitting the leg, the switch raising cam 419 and the switch lowering cam 415 are brought into action from the lug 851 on the pattern chain. This raises all the needles except the group of central needles with .240 butts shown in the lower half of the needle arrangement in Fig. 34 to an inactive level by travelling up a path which is identified in Fig. 1 by the letter E. These raised needles meet the hump 38 on the double center stretch cam 50 and pass over

the cam (Fig. 18). This is considered the first stroke in the making of the heel.

The machine now begins to reciprocate. The first stage of narrowing in the heel is to narrow on the needles of the group whose butts are .240 in length. These are the shortest butt needles in the machine. On the first stroke or oscillation in the reverse direction the first two needles of the active group with the .240 butts are raised up out of action by a lifter or up-pick 658 as shown in Fig. 20. This occurs shortly before the needles reach the double center stitch cam 50 and therefore these two needles N¹ and N² ride up the left-hand side of the hump 38 on the center stitch cam. As can be seen in Fig. 21, while these two needles and the ones preceding them at the inactive level are riding up the hump of the stitch cam, the sinkers are retracted by the left-hand sinker retracting cam 301.

The sequence with regard to the raising of needles N¹ and N² to the inactive level is as shown in Figs. 23 to 26. The arrow in Fig. 23 indicates the rotary direction of knitting. The courses of the heel marked a and b are part of the last complete rotary courses and the courses marked c and d are the first partial courses of the heel. As the needle cylinder starts in the reverse direction for the first time, the last active needle N¹ and its adjacent needle N² are picked out of action by the widening picker 650 as shown in Fig. 20. It is on this stroke that courses c and d are made. After the last active needles N¹ and N² have been raised by the widening picker and have ridden over the hump 38 of the double center stitch cam 50 the needles and fabric are in the position of Fig. 23 of the drawings. This corresponds approximately to the position of the parts in Fig. 21. It will be noted that the sinker retracting cam 301 in the sinker cam cap 300 has permitted the stitches on the inactive needles to be raised above the nebs W¹⁰ of the sinkers as the needles rise up over the hump of the stitch cam. (The arrows in Figs. 20 and 21 show that the needles are moving in the reverse direction.) On this reverse stroke after the needles N¹ and N² are raised to the inactive level, the remainder of the active needles knit a course e under the double stitch cam 50. After the needles have knit this course but before they reach the second feed the fabric will look as it is shown in Fig. 24. Immediately thereafter the needles knit a second course by passing under the right-hand end stitch cam 361, and the fabric now appears as shown in Fig. 25. This course knit at the right-hand throat plate is designated by the letter f. Since on any two successive movements of the needle cylinder in opposite directions it is the same yarn which is knit, it follows that the yarn knit last at one throat plate is the first to be knit when the machine reverses direction so that throughout the toe and heel the fabric consists of consecutive groups of two courses each of the same yarn. After the machine has knit in the reverse direction as shown in Fig. 25, it will of course move again in the forward direction and the first yarn to knit will be the one at the right-hand throat plate, namely, the yarn YR as shown in Fig. 26. Thereafter, of course, the yarn YL from the left-hand throat plate will knit and the relations of the free yarn ends to the needles will then be approximately the same as in Fig. 23. However, as soon as the machine starts moving in the reverse direction again the next two needles N⁵, N⁶ will be raised to idle level in the same manner that the needles N¹, N² were raised to inactive

level on the previous reciprocation. It might be pointed out that simultaneously with the cycle of operations just described with relation to one end of the active group of needles, a similar situation is building at the opposite end of the active group. Thus for example the last active needle on the opposite end of the short butt group of needles on which the heel is being made knits yarn from both feeds on the first stroke in the reverse direction and is then raised to inactive position with the adjacent needle when the machine starts moving in the forward direction again. These movements are illustrated in Figs. 20 and 21 where the arrow indicates that the needles are moving in a rotary direction. In Fig. 20 the two needles which were the last to knit on the last rotary movement of the cylinder are shown being raised to indicate their level on the first reverse movement while Fig. 21 shows the remaining needles passing under the double center stitch cam 50.

The unusual picking just described causes each yarn to float across in front of the two newly raised needles when each end is the leading end of the active group. At this time they knit into the needle wales adjacent to them in the next course. The net result of this peculiar manipulation is that the yarns cross over each other and there is a point between the needles N¹ and N² where there is a bight of yarn that floats across the two needles. These bights are subject to damage by the sinkers when they are pushed in by the sinker cams. The above-mentioned hump cams 38 and 39 overcome this danger. With this construction when the sinkers are returned immediately after passing the cam 38 or the cam 39 they will pass under these "tie-across" yarns without damaging them.

Reciprocation as above described continues until say 38 of the needles with .240 butts have been raised at each end of the active segment of needles. The machine then begins to make another narrowed segment of the heel by inserting the switch lowering cam 415 into action. This restores all the needles to active level. Immediately the switch raising cam 419 raises again to the inactive level all the needles except those having butts which are .240 or .270 in length. As pointed out above, at the time that the needles reach the switch lowering and switch raising cams 415 and 419, all of the loops are still above the nebs of the sinkers as a result of what happened on the hump on the double stitch cam 50.

It would be dangerous to have the switch raising cam 419 raise those needles whose loops are still above the nebs and therefore I insert the special sinker retracting cam 391 in conjunction with the switch draw-down cam 415. This is accomplished by the mechanism in Figs. 15 and 16. Shortly prior to the time that it is desired to insert the special sinker retracting cam 391 the lower arm of the bell crank lever 516 (Fig. 16) rides up on drum cam 502 moving the upper arm of the bell crank lever toward the safety linkage. The pin 516a on the upper end of the upper arm of the bell crank lever 516, sliding on the wire 515, compresses the spring 517 so as to exert pressure on the wire 515 towards the safety linkage 518, 511. When the side lug 851 on the pattern chain 85 comes under the lug reading arm 392, the bar 510 of the safety linkage will be drawn down to the limit, thereby permitting the pressure being exerted by the wire 515 to reset the latch and pin 512, 513. This pulling down of the bar 510 will rock the bell crank

395 about its pivot on the bedplate of the machine, swinging the arm 383 to the left as it appears in Fig. 15 and away from the lever 384. The lost motion connecting rod 385 between arm 383 and lever 384 pulls the latter towards the vertical pin 386, releases its pressure against the flat plate lever 387 and the sinker cam 391 will be inserted by a pressure spring associated with it (not shown). When the side lug 851 on the pattern chain rides out from under the reader arm 392, the bell crank lever, rocking on its center, permits tension spring 383a attached to the arm 383 to push the vertical pin to the right which, as can be seen from Fig. 15, swings the sinker cam 391 radially outward. This carries the sinkers with it, thereby permitting such yarn loops as are still above the nebs of the sinkers to go below the level of the nebs. The needles pass the sinker retracting cam 391 in time for the nebs to catch the loops before the needles are pushed up again by the switch raising cam 419. It will be noted that the riding of the reader arm 392 up onto the side lug 851 on the pattern chain also acts through bell crank lever 395 and the tie rod 396 to pull the linkage 397 and bell crank lever 398 to insert the switch draw-down cam 418.

Reciprocation of the needle cylinder continues and the up-picks 650 now raise the remaining three .270 butt needles and thirty-one of the .240 butt needles on each side of the .240 butt group. The machine then proceeds to make a widened gusset, i. e., the bottom or last gusset of the Sheppard Patent 2,388,649 above referred to. This is done by again changing the selection of needles by using the switch lowering cam 415 and the switch raising cam 419. The sinker retracting cam 391 operates again as above described. During this third gusset the up-picks 650 continue to operate but raise only one needle instead of two. This change in operation is accomplished by moving the slide 651 shown in Figs. 27 and 28 in the manner already described.

Simultaneously with this change in the up-picks, the dropper 680, goes into action, bringing down three inactive needles at each oscillation until a net amount of four needles in all have been drawn down at each end of the active group. This action of the dropper can be seen in Fig. 22. A word of explanation about this figure may be useful. At the right-hand throat plate in this figure it will be observed that one needle is higher than the other. The lower needle is the one which has just been raised by the narrowing pick and it has not yet ridden up the hump 39 of the double center cam. This butt has come off the end of the narrowing pick as the latter swings about its pivoted center and hence its position apparently in back of the pick as the parts appear in Fig. 22. As soon as the net increase of four has been obtained, the switch lowering cam 415 again goes into action and restores all inactive needles to active level 30.

To end the retraction of the sinkers by the sinker cam 391 the movement of the main pattern drum can be employed to turn the drum cam 502 from under the leg of the lower arm of bell crank lever 516. When the bell crank lever drops down onto the surface of the pattern drum, the wire 515 is pulled away from the safety linkage 510, 511, thereby unlatching the latch 512 from the pin 513, causing the bell crank lever 395 to drop. This not only causes the arm 383 to move to the left as it appears in Fig. 15 and

10 release the sinker retracting cam 391, but also retracts the lowering cam 415.

15 The machine then changes from reciprocating to rotary knitting and the knitting of the foot of the stocking commences. After the foot has been knit, a ring toe can be made. This can be done conveniently at this time. The starting of the ring toe is a convenient time to introduce the lowering cam 23 which brings down all the .338 and .390 long butt needles until they reach the lower transfer height C. These constitute one-half the needles of the machine. This gets the long butts out of the way momentarily and at the end of the ring toe the switch raising cam 419 is 20 inserted to raise the short butt needles out of action during the making of the toe on the long butt half of the needle cylinder. This is the instep side. After raising the short butt needles above mentioned, the switch raising cam 419 comes out of action. Simultaneously the cam 25 23 is retracted, so that the needle cylinder can now start to reciprocate.

25 On the first stroke in the toe the needle cylinder picks up two needles and continues raising two at each reversal of direction until approximately all of the .338 and .390 butt needles are raised, leaving in active position only the middle group of .338 butt needles. For example in a 30 400-needle machine this would mean that 58 needles are raised at each end of the group at this stage of making the toe. The machine continues to raise two needles at each change of direction and cams are inserted to bring down the .390 butt needles from the inactive to the active position. For this purpose the so-called 35 second group of .390 butt needles are brought down by the cam 32 located adjacent the switch raising cam 419 and the first group of .390 butt needles are brought down by a cam 33 located just ahead of the cam 23. On the end of this 40 stroke in the forward direction when the new cams are inserted they are both again removed. The needles which are raised to the inactive level at this time will knit when they return to activity before they rise again to the inactive 45 level. Therefore it is not absolutely necessary that the special sinker retracting cam 391 be used.

50 The active group now is the group which begins at the longest point of the gusset and the picks begin raising the .390's two at a time at each end to make the toe gusset. It should be pointed out that before this picking up begins again all the needles that were drawn down, namely, all 55 the .390's, have gone through two knitting waves. In this way the full course yarns have been knitted in and cast off along with the stitches which were on the shanks of the needles before the first picking up began. The new picking, 60 of course, starts a new series of tie-across yarns located at the tapered ends of the gusset. There are five complete reciprocations making the new series of tie-across yarns by picking up two needles at each end on each reciprocation. Then 65 the pattern drum 120 makes what is known as the second gusset rack. As a result the switch raising cam 419 goes in over the middle .338 group of needles, i. e., not raising them but on top of them, so that the cam will catch and raise the 70 .390's when they come around. This raises the second group of .390 butt needles out of action and the corresponding or auxiliary raising cam 34 on the other side of the machine raises the first group of .390 butt needles. The insertion of 75 these two switch raising cams occurs on a for-

ward stroke of the needle cylinder. At the end of that stroke both switch cams come out of action and the dropper pick 680 is thrown into action, over the middle .338 group of needles which are the only needles now down in knitting position. The gusset is now made and we are ready to go off the gusset onto the remainder or bottom of the toe fabric.

The dropper 680 lowers the three .390 butt needles adjacent the middle .338 group in what is termed the first .390 group, the machine now turning in the reverse direction. This dropper brings these needles down before any of the needles pass through either of the knitting waves. In the meantime the raising or up-picks have been changed from two to one needle operation. The up-pick catches and raises the last needle of the middle group of .338 butts, raising it to inactive level before it goes through the two knitting waves. While we have raised the .338 butts at one end of the middle .338 butt group, the .390 butt needles adjacent that group which were just lowered are adjacent the opposite end of the middle .338 butt group, so that there still is one continuous group of active needles. What has been done is to shorten the active group at one end and lengthen it at the other. On the following forward stroke the dropper will lower the .338 butt needles which were just raised out of action, together with the two adjacent .390 butt needles to an active level, and the right-hand up-pick 650 will raise one of the .390 butt needles which were lowered into action by the dropper on the previous oscillation and the needles go through the two knitting waves. This sequence of raising and lowering is kept up until all the needles with which the toe was started have worked back into action, namely, half the needles in the machine. A down-pick lowers the last .338 butt needles in the last group and the machine is ready to change from reciprocatory to rotary knitting.

In coming out of the toe the switch draw-down cam 415 is inserted against the cylinder while the middle group of .338 butt needles is passing on the first rotary or forward movement of the machine after the making of the toe. As a result all short butt needles, i. e., all those in that half of the circle which were in at the inactive level, are lowered again to the active level. Approximately thirty courses are now knit to form the loopers rounds. As already explained, contrary to previous practice, when the loose course for looping was normally made on the first course after the toe, I now make this loose course the second course after the toe. This is done in the following manner. Referring to Fig. 17, a rack of the main pattern drum 120 brings a drum cam 503 under a thrust rod 462 which, acting through a lug 583 on the thrust bar, tips a lever 466 about its pivot point 465 so as to engage and push downwardly on a pin 364 extending radially outward from the left-hand end stitch cam 360. Since it is under this stitch cam that the yarn fed in the second feed is knit on rotary movement of the needle cylinder, it follows that as long as the thrust bar 462 is held up by the drum cam 503, the stitches knit at the left-hand feed will be longer than usual. After one complete revolution of the machine it is therefore necessary to return the above stitch cam to its normal position. As already explained, this is done by the lever arm 467 on the thrust bar coming in contact with the pin 469 on the collar 488 on the main drive shaft 322 of the machine, thereby

knocking the lower end of the thrust rod off the cam 503.

If it is desired to make the delayed transfer welt of Fig. 29, the projection of the transfer jacks 5 takes place at the beginning of the third revolution of the machine by the insertion of cam 297.

It may be noted that the bevels 562, 563 and the hump cams 38 and 39 have similar effects in that they both serve to raise the yarn so as to avoid 10 damage by the sinkers. This is true whether the upper part of the yarn is raised by the bevel, the lower part of the yarn is raised by elevation of the stitches and the fabric, or the tie-across construction is being raised with relation to the 15 sinkers.

While I have shown retraction of the raise cam 353 between the leading end cam 361 in the rotary direction and the double stitch cam 50, it should be understood that if it is desired to have the 20 needle follow a non-knitting path at the following end cam 360, then the raise cam 352 following the double end cam would be retracted. In this case the adjacent stitch cam where the 25 needles would knit would be the double stitch cam.

It will be seen that in spite of the difficulties of operating a hosiery knitting machine continuously on a multiple number of feeds beginning on the bare needles and carrying through the 30 automatic inturned welt and heel and toe involving successively different selections of needles at each of those parts of the stocking, I have produced a simple and coordinated machine and method to overcome all the needle and sinker 35 difficulties and produce a fine-gauge stocking at high speed, including the yarn changes which are so necessary in modern fine-gauge stockings. I am the first to have yarn changes in a double feed machine where there is reciprocatory knitting. I am the first to use a multiplicity of yarn 40 fingers in throat plates in a multi-feed hosiery machine which knits multi-feed both in the rotary and reciprocatory manner.

What is claimed is:

- 45 1. A circular independent needle hosiery knitting machine adapted to knit a stocking with reciprocatory heel and toe all by multi-feed knitting, in which there are a multiplicity of switch cams, a plurality of said cams being adapted to knit in the forward direction and a plurality in the reverse direction, in combination with means associated with the stitch cams causing selvedge start-up of the stocking while the machine is knitting multi-feed.
- 50 2. A circular independent needle hosiery knitting machine adapted to knit a stocking with reciprocatory heel and toe all by multi-feed knitting, in which there are a multiplicity of stitch cams, a plurality of said cams being adapted to knit in the forward direction and a plurality in the reverse direction in combination with means associated with the stitch cams causing the making of a turned welt while the machine is knitting multi-feed.
- 55 3. A circular independent needle hosiery knitting machine adapted to knit a stocking with a turned welt and multi-feed heel and toe according to claim 2 in which there is a plurality of independent sinkers with nebs to hold down 60 stitches in combination with means adapted to change the maximum number of active needles during multi-feed reciprocatory knitting.
- 65 4. A circular independent needle hosiery knitting machine adapted to knit a stocking with a turned welt and reciprocatory heel and toe all knit multi- 70

feed, in which there is a multiplicity of stitch cams in combination with means adapted to cause needles temporarily to take a non-knitting path at one stitch cam but a knitting path at another, whereby the machine is adapted to make a multi-feed turned welt.

5. A circular independent needle hosiery knitting machine adapted to knit a stocking with a turned welt and multi-feed heel and toe, in which there are a multiplicity of stitch cams in combination with means of which part is a movable raise cam adapted to cause needles to take a non-knitting path at one stitch cam, said means and one of the stitch cams being adapted to cause the needles to take a knitting path at a stitch cam other than said first stitch cam, whereby the machine is adapted to make a multi-feed turned welt.

6. A circular independent needle multi-feed hosiery knitting machine adapted to knit a stocking with a turned welt and two-feed heel and toe, in which there are at least three stitch cams adapted in either direction of knitting to knit at a multiplicity of feeds one less in number than the number of stitch cams, in combination with means of which part is a movable raise cam adapted to cause needles to take a non-knitting path at one stitch cam whereby the machine is adapted to make a multi-feed turned welt.

7. A circular independent needle multi-feed hosiery knitting machine adapted to knit a stocking with a turned welt and two-feed heel and toe, in which there are three stitch cams adapted in either direction of knitting to knit two courses in combination with means adapted to cause needles temporarily to take a non-knitting path at one stitch cam but a knitting path at another, whereby the machine is adapted to make a multi-feed turned welt.

8. A circular independent needle two-feed hosiery knitting machine adapted to knit a stocking with a turned welt and two-feed heel and toe in which there are two end stitch cams and a center stitch cam, the latter having separate surfaces adapted to knit on rotary and reciprocatory movements respectively, and the end cams acting as clearing cams when in the leading position, said three stitch cams being relatively stationary during the knitting of the welt, in combination with means adapted to cause needles to take a non-knitting path at the leading stitch cam whereby the machine is adapted to make a two-feed start-up from the bare needles.

9. A circular independent needle hosiery knitting machine adapted to knit multi-feed on both rotary and reciprocatory knitting in which there are two end stitch cams and one or more intermediate stitch cams and raise cams adjacent one of the intermediate stitch cams adapted to raise those needles that have passed under the intermediate cam in either direction in order that they may knit at the next stitch cam, in combination with mechanism adapted to retract one of said raise cams, whereby needles take a non-knitting path at a desired stitch cam and knit at an adjacent stitch cam.

10. A circular independent needle hosiery knitting machine adapted to knit multi-feed on both rotary and reciprocatory knitting in which there are two end stitch cams and one or more intermediate stitch cams, and raise cams adjacent one of the intermediate stitch cams adapted to raise needles that have passed under the intermediate cam in either direction in order that they may knit at the next stitch cam, in combination with

mechanism adapted to move a raise cam out of action whereby a non-knitting path is clear for needles at a desired stitch cam and they can knit at an adjacent stitch cam.

5. 11. A circular independent needle hosiery knitting machine adapted to knit multi-feed on both rotary and reciprocatory movements in which there are at least three stitch cams in combination with a cam between the leading stitch cam in the forward direction and the adjacent stitch cam adapted to raise needles for knitting that have come under the adjacent cam on a reverse movement, and means adapted to retract the raise cam out of action for a forward movement, whereby needles can be led under the leading stitch cam on forward movements and the machine can start up from the bare needles with all feeds in action.

20 12. A circular independent needle hosiery knitting machine according to claim 11, in which the leading stitch cam in the forward direction is shaped so that it is adapted to clear needles for knitting by the adjacent cam or lead them down to go under the adjacent cam without clearing or taking yarn, whereby the machine is adapted to make a stocking welt multi-feed.

25 13. A circular independent needle hosiery knitting machine adapted to knit multi-feed on both rotary and reciprocatory movements, in which there are at least three stitch cams, the leading stitch cam in the forward direction being adapted to knit on a reverse movement in combination with a cam between the adjacent and leading cams adapted on reverse stroke to raise needles coming under the adjacent cam and permit the leading cam to knit, and means to retract said raise cam, whereby on forward movements the leading cam can present needles at two levels to the adjacent stitch cam.

30 14. A circular independent needle hosiery knitting machine adapted to knit multi-feed on both forward and reverse movements in which there is at least one double cam adapted to knit on both movements, a side stitch cam located ahead of said double cam on forward movements, and a stitch cam located after the double cam on the same direction of movement, in combination with a cam adapted to raise needles coming under the double cam on reverse movements preparatory to knitting on the side stitch cam, and means adapted to withdraw the raise cam when it is desired to pass needles under the side cam on a forward movement, whereby the machine can start up from the bare needles with all knitting feeds in action and make an inturned welt.

35 15. A circular independent needle hosiery knitting machine adapted to knit multi-feed on both rotary and reciprocatory movements in which there are at least three stitch cams, a cam between the leading stitch cam in the forward direction and the adjacent stitch cam adapted to raise needles for knitting that have come under the adjacent cam on a reverse movement, and means adapted to retract the raise cam out of action for a forward movement, in combination with a movable dividing cam adapted to direct spaced needles under the leading stitch cam in the rotary direction of movement so that all needles knit after the double stitch cam, whereby the machine starts up from the bare needles and completes the welt multi-feed without changing the knitting cams.

40 16. A circular independent needle hosiery knitting machine adapted to knit multi-feed on both rotary and reciprocatory movements in which

there are at least three stitch cams, a movable raise cam associated therewith and a movable dividing cam adapted to direct spaced needles under the leading stitch cam in the rotary direction of movement so that all needles knit after the adjacent stitch cam, in combination with transfer jacks, whereby the machine can start up from the bare needles and complete the welt multi-feed without changing the knitting cams.

17. A circular independent needle hosiery knitting machine adapted to knit multi-feed on both rotary and reciprocatory movements, in which there are at least three stitch cams, the leading cam in the forward direction being adapted to knit on a reverse movement and adapted on a forward movement to cause needles to approach the adjacent stitch cam at two levels, such adjacent cam having separate stitch-drawing surfaces adapted to knit on directions of knitting movement opposite to each other, in combination with a cam between the leading and such adjacent stitch cam adapted on reverse stroke to raise needles so that both the adjacent and leading stitch cams knit, and means to remove said raise cam for a movement in the forward direction, whereby the needles are adapted to approach the adjacent stitch cam at either of two levels.

18. A circular independent needle hosiery knitting machine adapted to knit multi-feed on both rotary and reciprocatory movements in which there are at least three stitch cams, a cam between the leading stitch cam in the forward direction and the adjacent stitch cam adapted to raise needles for knitting that have come under the adjacent cam on a reverse movement, means adapted to retract the raise cam out of action for a forward movement and a movable dividing cam adapted to direct needles under the leading stitch cam in the rotary direction of movement, in combination with a dial, transfer jacks in the dial and a cam in the dial adapted to press the jacks outwardly at a feed subsequent to the leading feed in a rotary direction, whereby the strain of the transfer jack hooks and the needle hooks on the yarn at the beginning of the make-up is relieved.

19. A circular independent needle hosiery knitting machine according to claim 18, in which the jack presser cam is pivoted at a circumferentially fixed point, in combination with a ring floating about the center of the dial to move the cam into operation.

20. A circular independent needle hosiery knitting machine adapted to knit at two feeds on both rotary and reciprocatory movements, a set of three stitch cams, two throat plates to feed yarn to the two trailing cams on each direction of knitting, the leading stitch cam on each direction of movement being adapted to raise needles to take yarn to knit at the next stitch cam, in combination with movable means directing spaced needles under the leading stitch cam and also permitting same to rejoin the intervening needles and knit at the third stitch cam for a plurality of revolutions of the machine, whereby the machine can start knitting on the bare needles with all feeds in action.

21. A circular independent needle hosiery knitting machine according to claim 20 in which the center cam has two separate surfaces adapted to draw stitches on directions of knitting movement opposite to each other and two throat plates are provided to feed yarn to the needles on both directions of movement, in combination with means adapted to permit only spaced needles to take

yarns at one knitting cam for a plurality of courses but permitting all the needles to take yarn and knit at the other cam during those courses, whereby knitting is started on the bare needles.

22. A circular independent needle hosiery knitting machine adapted to knit at two feeds on both rotary and reciprocatory movements, in which there is a set of three stitch cams comprising a center cam having two separate draw-down faces adapted to draw stitches for the first of the two courses in directions of movement opposite to each other and two end stitch cams each adapted to act as a clearing cam when the needles approach from its end and to knit when they approach from the center cam, in combination with a raise cam below one side of the center stitch cam adapted to assist in clearing for the following end stitch cam needles which have drawn stitches under the center cam on movement in the reverse direction, a dividing cam adapted to lead spaced needles which are not to take yarn under the leading stitch cam in the forward direction of movement, and control means withdrawing the said raise cam and inserting said dividing cam for a plurality of forward revolutions of the machine in order that the machine may start knitting on the bare needles without changing the knitting cams during the makeup.

23. A circular independent needle hosiery knitting machine adapted to knit multi-feed on both rotary and reciprocatory movements in which there are at least three stitch cams, a cam between the leading stitch cam in the forward direction and the adjacent stitch cam adapted to raise needles for knitting that have come under the adjacent cam on a reverse movement, means adapted to retract the raise cam out of action for a forward movement, and a plurality of independent sinkers therein having nebs adapted to hold down stitches, in combination with means adapted to raise one or more of the yarns as they lie from the yarn feeds to the last needle to knit during reciprocatory movements whereby damage to the yarn by the sinkers is prevented.

24. A circular independent needle hosiery knitting machine according to claim 23, in which there is in the means to raise the angle of the yarn to the last needle to knit means adapted to elevate the idle needles slightly at a point where the sinkers are retracted by a sinker retracting cam, whereby the stitches on the idle needles can be temporarily elevated above the nebs of the sinkers and cutting or breaking of the yarn prevented.

25. A circular independent needle hosiery knitting machine adapted to knit multi-feed on both rotary and reciprocatory movements in which there are at least three stitch cams, a plurality of yarn feeds and independent sinkers having nebs adapted to hold stitches adjacent, in combination with means adapted to raise one or more of the yarns as they lie from the yarn feeds to the last needle to knit during reciprocatory movements whereby damage by the sinkers to the yarn is prevented.

26. A circular independent needle hosiery knitting machine adapted to knit multi-feed on both rotary and reciprocatory movements in which there are at least four stitch-drawing surfaces, a plurality of throat plates at least two less in number than the stitch-drawing surfaces adapted to feed yarn to the needles on both rotary and reciprocatory movements, and

a plurality of yarn fingers in each throat plate whereby yarns can be changed, in combination with a plurality of independent sinkers having nebs adapted to hold stitches down and means adapted to protect the stitches or yarn against damage by the sinkers.

27. A circular independent needle hosiery knitting machine adapted to knit multi-feed on both rotary and reciprocatory movements in which there are at least three stitch cams, a plurality of throat plates less in number than the stitch cams adapted to feed yarn to the needles on both rotary and reciprocatory movements, and a plurality of yarn fingers in each throat plate whereby yarns can be changed, in combination with a plurality of independent sinkers having nebs adapted to hold stitches down and means adapted to raise one or more of the yarns as they lie from the throat plates to the last needle to knit during reciprocatory movements whereby damage by the sinkers is prevented.

28. A circular independent needle hosiery knitting machine adapted to knit multi-feed on both rotary and reciprocatory movements in which there are at least three stitch cams, a cam between the leading stitch cam in one direction and the adjacent stitch cam adapted to raise needles for knitting that have come under the adjacent cam on a movement in the opposite direction, means adapted to retract said raise cam out of action for a movement in the first direction and a plurality of independent sinkers having nebs adapted to hold stitches down, means adapted to raise one or more of the yarns as they lie from the yarn feeds to the last needle to knit during reciprocatory movements, said raising means comprising in part a switch cam adapted to raise needles out of action as a group shortly before the machine begins a reverse movement, a sinker retracting cam, and a hump on a stitch cam adapted to raise such idled needles slightly at the point where the sinkers are retracted, whereby the stitches on the last active needle will be held at a higher level than otherwise and damage to the yarn by the sinkers is prevented.

29. A circular independent needle hosiery knitting machine adapted to knit multi-feed on both rotary and reciprocatory movements in which there are at least three stitch cams, a plurality of throat plates less in number than the stitch cams adapted to feed yarns to the needles on both rotary and reciprocatory movements, and a plurality of yarn fingers in each throat plate whereby yarns can be changed, in combination with a plurality of independent sinkers having nebs adapted to hold stitches down and means adapted to raise stitches on the idle needles over the sinker nebs, whereby damage to the stitches on the idle needles by the sinkers is prevented.

30. A circular independent needle hosiery knitting machine adapted to knit multi-feed on both rotary and reciprocatory movements in which there are at least three stitch cams, a cam between the leading stitch cam in one direction of movement and the adjacent stitch cam adapted to raise needles for knitting that have come under the adjacent stitch cam on the other direction of movement, means adapted to retract the raise cam out of action for a movement in the first direction, a plurality of independent sinkers having nebs adapted to hold stitches down, and a sinker retracting cam, in

combination with a hump on the top of a stitch cam adapted to elevate the idled needles slightly at a point where the sinkers are retracted by the sinker retracting cam for the purpose described.

5 31. A circular independent needle hosiery knitting machine adapted to knit multi-feed on both rotary and reciprocatory movements in which there are at least three stitch cams, a cam between the leading stitch cam in the forward direction of movement and the adjacent stitch cam adapted to raise needles for knitting that have come under the adjacent stitch cam on a reverse movement, means adapted to retract the raise cam out of action for a forward movement, a plurality of independent sinkers having nebs adapted to hold stitches down, and a sinker retracting cam, in combination with an up-pick and a hump on a stitch cam to elevate the leading active needle or needles which are thrown up out of action by the up-pick just before they pass through the stitch cams, whereby the lower ends of the yarns from the yarn feeds to those needles are elevated above the nebs of the sinkers.

10 32. A circular independent needle hosiery knitting machine adapted to knit multi-feed on both rotary and reciprocatory movements in which there are at least three stitch cams, a cam between the leading stitch cam in a rotary direction of movement and the adjacent stitch cam adapted to raise needles for knitting that have come under the adjacent cam on a reverse movement, means adapted to retract said raise cam out of action on a movement in the rotary direction and a plurality of independent sinkers having nebs adapted to hold down stitches, a sinker retracting cam, means adapted to raise the angle of one or more of the yarns as they lie from the yarn feeds to the last needle to knit during reciprocatory movements, and means adapted to elevate the idled needles slightly at a point where the sinkers are retracted, in combination with a needle selecting means located prior to the knitting wave in the rotary direction to draw down one group of needles, and a second needle selecting means to raise a different selection of needles, the sinker retracting cam being adapted to hold sinkers out opposite the first means but not the second, whereby the selection of needles being used in reciprocatory knitting can be changed without increasing the special elevation of stitches above the nebs of the sinkers.

15 33. A circular independent needle hosiery knitting machine adapted to knit multi-feed on both rotary and reciprocatory movements in which there are at least three stitch cams, a plurality of independent sinkers having nebs adapted to hold down stitches, a sinker retracting cam, means adapted to raise the angle of one or more of the yarns as they lie from the yarn feeds to the last needle to knit during reciprocatory movements, and means adapted to elevate the idled needles slightly at a point where the sinkers are retracted, in combination with a needle selecting means located prior to the knitting wave in the rotary direction to draw down one group of needles, and a second needle selecting means to raise a different selection of needles, the sinker retracting cam being adapted to hold sinkers out opposite the first means but not the second, whereby the selection of needles being used in reciprocatory knitting can be changed without increasing the special ele-

vation of stitches above the nebs of the sinkers.

34. A circular independent needle knitting machine adapted to knit multi-feed on both rotary and reciprocatory movements in which there are at least three stitch cams, a sinker cap adapted to oscillate for reciprocatory knitting on all feeds, and independent sinkers controlled by the cap having nebs adapted to hold stitches down, in combination with means adapted to raise stitches on the idle needles over the sinker nebs, whereby damage to the stitches on the idle needles by the sinkers is prevented.

35. A circular independent needle knitting machine according to claim 34 in which as part of the means to raise stitches there is a hump on one of the stitch cams in combination with sinker retracting means in the cap adapted to retract the sinkers while the needles rise over the hump, whereby the stitches on the idle needles are raised above the sinker nebs during reciprocatory knitting.

36. A circular independent needle knitting machine according to claim 35 in which as part of the means to raise the stitches there is a switch cam adapted to raise needles out of action as a group shortly before the machine begins a reverse movement and the hump on a stitch cam is adapted to raise such idled needles slightly at the point where the sinkers are retracted, whereby the fabric on the last active needle will be held at a higher level than otherwise.

37. A circular independent needle knitting machine according to claim 36 in which there is a needle selecting means located prior to the knitting waves in the rotary direction, there being in said means a cam to draw down one group of the needles, and a second cam to raise a different selection of needles, and the sinker withdrawing cam is adapted to hold out sinkers opposite the first cam but not the second, whereby the selection of needles being used in reciprocatory knitting can be changed without increasing the special elevation of stitches above the nebs of the sinkers.

38. A circular independent needle knitting machine adapted to knit multi-feed on both rotary and reciprocatory movements, in which there are a plurality of throat plates, at least three stitch cams, a sinker cap adapted to oscillate for reciprocatory knitting on all feeds, and independent sinkers controlled by the cap having nebs adapted to hold stitches down, in combination with up-picks adapted on reciprocatory knitting to elevate a plurality of the leading active needles before they pass through the knitting cams, and a hump on one of the stitch cams adapted to further elevate said plurality of needles immediately thereafter and while the sinkers are retracted at the knitting point, whereby the tie-across yarns in front of the needle raised by the pick are elevated above the nebs of the sinkers.

39. A circular independent needle hosiery knitting machine adapted to knit multi-feed on both rotary and reciprocatory movements in which there are at least three stitch cams, a cam between the leading stitch cam in one direction and the adjacent stitch cam adapted to raise needles for knitting that have come under the adjacent cam on a movement in the opposite direction, means adapted to retract said raise cam out of action on a movement in the first direction, a plurality of independent sinkers having nebs adapted to hold stitches down,

means adapted to raise the angle of one or more of the yarns as they lie from the yarn feeds to the last needle to knit during reciprocatory movements, said yarn-raising means comprising in part a sinker retracting cam and a plurality of throat plates to feed yarn to the needles, the end of each throat plate at the corner where the yarn feeds when that throat plate is feeding in trailing relation to the other being bevelled, whereby after the last needle to knit during reciprocatory movements has drawn yarn, the yarn will rise on the bevel, raising the angle of the trailing yarn going to that needle.

40. A circular independent needle hosiery knitting machine adapted to knit multi-feed on both rotary and reciprocatory movements in which there are at least three stitch cams, a plurality of independent sinkers having nebs adapted to hold stitches down, means adapted to raise the angle of one or more of the yarns as they lie from the yarn feeds to the last needle to knit during reciprocatory movements, said yarn-raising means comprising in part a sinker retracting cam and a plurality of throat plates to feed yarn to the needles, the end of each throat plate at the corner where the yarn feeds when that throat plate is the first to feed in relation to the other being bevelled, whereby after the last needle to knit during reciprocatory movements has drawn yarn, the yarn will rise on the bevel, raising the angle of the trailing yarn going to that needle.

41. A circular independent needle hosiery knitting machine adapted to knit multi-feed on both rotary and reciprocatory movements in which there are a plurality of stitch cams and throat plates and a plurality of yarn fingers in at least one throat plate, the throat plates being adapted to feed yarn to the needles on both rotary and reciprocatory movements, further characterized in that the end or ends of each throat plate are bevelled at the corner or corners where the yarn feeds when that throat plate is feeding in following relation to another, whereby when the last needle to knit during reciprocatory movements has drawn yarn, the yarn will rise on the bevel raising angle of that yarn.

42. A circular independent needle hosiery knitting machine adapted to knit multi-feed on both rotary and reciprocatory movements in which there are at least three stitch cams, a plurality of throat plates and a plurality of yarn fingers in each throat plate whereby yarns can be changed, in combination with a hump on the top of one of the stitch cams, a bevel at the end or ends of each throat plate where the yarn feeds when the throat plate is feeding in following relation to another, and a latch opening angle above each bevel, said hump being so located that it is raising the needle when the needle is passing the latch opening angle.

43. A circular independent needle hosiery knitting machine adapted to knit multi-feed on both rotary and reciprocatory movements in which there are at least three stitch cams, a plurality of throat plates and a plurality of yarn fingers in each throat plate, in combination with a depending lip on the bottom of each throat plate adapted to enter between the hook and latch of any needle where the latch is partly open and finish opening the latch, whereby damage to the latter is avoided.

44. In a method of producing a multi-feed welt on a circular independent needle multi-

feed hosiery knitting machine, the steps of retracting a raise cam located between two stitch cams, thereby causing needles to take a non-knitting path at one feed and to knit at another feed.

45. In a method of producing a multi-feed welt on a circular independent needle hosiery knitting machine having a multiplicity of stitch cams and a raise cam therebetween, the steps of retracting the raise cam and allowing the needles to approach the following stitch cam at two levels, whereby only certain needles knit at that stitch cam, and subsequently knitting on all needles at another stitch cam.

46. In a method of operating a circular independent needle hosiery knitting machine having a multiplicity of stitch cams and a raise cam between two of them, the steps of retracting the raise cam and causing the needles to approach the following stitch cam at two levels, projecting welt transfer elements in the making of the welt while the needles are at two levels and taking bights of yarn on such elements, and thereafter knitting on all needles at another stitch cam.

47. In a method of operating a circular independent needle multi-feed hosiery knitting machine having a plurality of yarn fingers at one or more feeds and adapted to knit multi-feed on both rotary and reciprocatory movements, the steps of knitting a welt with yarns from one selection of yarn fingers, changing the yarn fingers selection and knitting a leg, thereafter changing to a third yarn finger selection to knit a heel and toe, while using the same yarn fingers for the foot that were used in the leg.

48. In a method of operating a circular independent needle hosiery knitting machine having sinkers with stitch holding nebs and a plurality of pivoted yarn fingers and adapted to knit at two or more feeds reciprocatorily, the steps of knitting a heel or toe by reciprocatory knitting in which a course is knit on a group of needles in one direction, raising one or more end needles of that group over one of the stitch cams on the next oscillation before they knit, retracting the sinkers momentarily while such needle or needles are rising over the stitch cam whereby the loops on such needles will get above the nebs of the sinkers and thereafter drawing down idle needles into action while the sinkers are momentarily retracted whereby the yarns from the fingers are lowered under the nebs.

49. In a method of operating a circular independent needle hosiery knitting machine having sinkers with stitch holding nebs and a plurality of pivoted yarn fingers, and adapted to knit at two or more feeds reciprocatorily, the steps of knitting a welt with yarns from one selection of yarn fingers, changing the yarn finger selection and knitting a leg, thereafter changing to a third yarn finger selection and knitting a heel and toe by reciprocatory knitting in combination with the steps of knitting a course on a group of needles in one direction, raising one or more end needles of that group over one of the stitch cams on the next oscillation before they knit, retracting the sinkers momentarily while such needle or needles are rising over the stitch cam whereby the loops on such needles will get above the nebs of the sinkers and thereafter drawing down idle needles into action while the sinkers are momentarily retracted whereby the yarns from the fingers are lowered under the nebs.

50. In a method of operating a circular independent needle multi-feed hosiery knitting machine, the steps first of dividing the needles and knitting on only spaced needles at one feed, and second, knitting on all the needles at a subsequent feed, keeping up this sequence of steps for three or more revolutions of the machine, in combination with projecting the transfer jacks to take bights of yarn on the second revolution of the machine at one feed, and after knitting a plurality of additional courses, transferring the bights on the jacks back to the needles.

51. In a method of operating a circular independent needle hosiery knitting machine having sinkers with stitch-holding nebs and adapted to knit at two or more feeds reciprocatorily, the steps of knitting a course on a group of needles in one direction, raising one or more end needles of that group over one of the stitch cams on the next oscillation before they knit, and retracting the sinkers momentarily while such needle or needles are rising over the stitch cam, whereby any loops on such needles will get above the nebs of the sinkers, thereby preventing damage to the stitches.

52. In a method according to claim 51, the step of raising out of action on an oscillation before they knit the two needles which knit last on the previous oscillation, whereby a tie-across bight of yarn is created, and on the oscillation which raises them out of action, retracting the sinkers momentarily during part of the time while the needles are rising, thereby raising the tie-across bight above the nebs of adjacent sinkers.

53. In a method of operating a circular independent needle hosiery knitting machine having sinkers with stitch-holding nebs adapted to knit at two or more feeds reciprocatorily, the steps of raising a group of needles out of action while knitting on the preceding needles, further raising the leading needles of the inactive group a short distance while adjacent sinkers are momentarily retracted, thereby raising the level of the fabric on those needles and forming a ledge over which the yarn from the last active needle passes, thereby supporting it to pass above the sinker nebs.

54. In a method of operating a circular independent needle hosiery knitting machine having sinkers with stitch-holding nebs adapted to knit at two or more feeds reciprocatorily, the steps of knitting a course on a group of needles in one direction, raising one or more end needles of that group over one of the stitch cams on the next oscillation before they knit, and retracting the sinkers momentarily while such needle or needles are rising over the stitch cam, changing the selection of active needles during reciprocatory knitting by drawing down idle needles into action while the sinkers are momentarily retracted and then raising non-desired needles back up out of action while the sinkers are in action, whereby loops on inactive needles are kept under control.

55. A circular independent needle hosiery knitting machine adapted to knit multi-feed on both rotary and reciprocatory movements in which there are at least four stitch-drawing surfaces, a cam between the leading stitch-drawing surfaces 70 in the forward direction and the adjacent surface adapted to raise needles for knitting that have come under the adjacent surface on a reverse movement, and means adapted to retract the raise cam out of action for a forward movement, in combination with a pattern jack select-

ing means adapted to clear the needles, the surface after the leading surface in the rotary direction being adapted to knit such cleared needles, whereby only selected needles knit at the first feed and all needles knit at the next feed.

56. A circular independent needle hosiery knitting machine adapted to knit multi-feed on both rotary and reciprocatory movements in which there are at least three stitch cams, a cam between the leading stitch cam in the forward direction and the adjacent stitch cam adapted to raise needles for knitting that have come under the adjacent cam on a reverse movement, and means adapted to retract the raise cam out of action for a forward movement, the leading stitch cam in the forward direction being so shaped that it is adapted to clear needles for knitting by the adjacent cam or lead them down under the adjacent cam without clearing or taking yarn, in combination with a dial, transfer jacks in the dial and cam means adapted to project the jacks at the leading stitch cam on the second revolution of knitting, whereby the machine can start up from the bare needles with all feeds in action and knit a multi-feed welt.

57. A circular independent needle hosiery knitting machine adapted to knit multi-feed on both rotary and reciprocatory movements in which there are at least three stitch cams, a cam between the leading stitch cam in the forward direction and the adjacent stitch cam adapted to raise needles for knitting that have come under the adjacent cam on a reverse movement, and means adapted to retract the raise cam out of action for a forward movement, one of the stitch cams being mounted in a vertically movable manner so that when depressed it can draw slack loops in a following course in the rotary direction of knitting, in combination with pattern-

controlled means adapted to depress said stitch cam during rotary knitting, and tripping means actuated from a continuously driven part of the machine adapted to release the stitch cam from depressed position, whereby a slack course of loops for looping can be produced in a rotary course subsequent to the first course of loopers rounds.

5 58. In a circular independent needle hosiery knitting machine adapted to knit multi-feed on both rotary and reciprocatory knitting in which there are two end stitch cams and at least one intermediate stitch cam, the mounting in a vertically movable manner of a stitch cam following the leading stitch cam in the rotary direction so that when depressed it can draw slack loops, in combination with pattern-controlled means adapted to depress said stitch cam during rotary knitting, and tripping means actuated 10 from a continuously driven part of the machine 15 adapted to release the stitch cam from depressed position, whereby a slack course of loops for looping can be produced in a rotary course subsequent to the first course of loopers rounds.

Certificate of Correction

Patent No. 2,576,962

December 4, 1951

JOHN J. McDONOUGH

It is hereby certified that error appears in the printed specification of the above numbered patent requiring correction as follows:

Column 2, line 48, for "sections" read *section*; line 49, for "Fig. 8" read *Fig. 9*; column 3, line 28, for "needle" read *machine*; column 4, lines 9 and 10, for "Fig. 28" read *Fig. 8*; column 9, line 15, for "apvroaching" read *approaching*; column 17, line 10, for "involves" read *involves*; column 24, line 75, for "stretch" read *stitch*; column 30, line 48, for "switch" read *stitch*; column 32, line 24, strike out "to go"; column 34, line 62, for "adjacent" read *down*; column 38, line 47, after "raising" insert *the*; column 39, line 34, for "seeletion" read *selection*; column 40, line 69, for "surfaces" read *surface*;

and that the said Letters Patent should be read as corrected above, so that the same may conform to the record of the case in the Patent Office.

Signed and sealed this 18th day of March, A. D. 1952.
